SHOE SEWING MACHINES

Fred Ashworth, Wenham, and Joseph R. Ioannilli, Beverly, Mass., assignors to United Shoe Machinery Corporation, Flemington, N.J., a corporation of New Jersey

Application October 28, 1955, Serial No. 543,428

22 Claims. (Cl. 112—53)

The present invention relates to improvements in straight hook needle lockstitch shoe sewing machines of the McKay type similar to that disclosed in United States Letters Patent No. 2,670,701, granted March 2, 1954, in the names of the present inventors. Many of the features of the present invention, however, are not limited to effective use with such machines but are applicable with advantage more generally to sewing machines especially intended for operating upon any thick, heavy material.

The general purposes of the present invention are to provide a sewing machine of the nature indicated which will show greater reliability, operate upon work of greater thickness and reveal greater freedom from frequent adjustments than corresponding prior machines.

With respect to the provision of a machine for operating upon work of greater thickness than is within the range of prior machines, needle and awl reciprocating mechanisms are provided similar to those disclosed in an application for United States Letters Patent, Serial No. 409,152, filed February 9, 1954, in the names of the present inventors, now Patent No. 2,737,134, granted March 6, 1956, the successful operation of which is dependent to some extent upon the construction of universally jointed links for connecting the needle and awl to their reciprocating mechanisms, disclosed in an application for United States Letters Patent, Serial No. 349,872, filed April 20, 1953, now Patent No. 2,767,004, granted October 16, 1956, in the names of the present inventors.

In its preferred form the machine constructed according to the features of the present invention includes mechanism for improving the accuracy of thread measurement for each stitch inserted in material of substantial thickness, in which a single member acts as a thread controller for preventing erratic movements of thread engaging the other stitch-forming devices of the machine and as a thread measuring pull-off engaging the needle thread between a pair of thread locks mounted along the path of the thread running through the machine at the opposite side of the work from the needle. The use of a single thread engaging member for both the controller and the pull-off results in less abrasion and wear on the thread than is caused by the use of separate controller and pull-off members, which abrasion and wear on the thread is an increasing impediment to operation on extremely thick work. In the illustrated form of this feature, a stitch setting loop taker is provided and the combined controller and pull-off pulls back thread from each stitch before it is set, in an amount less than that required for retraction of the threaded needle from the work. In this way abrasion and wear on the thread being drawn through the work are reduced to a minimum.

Other features of the invention include a novel and improved presser foot mechanism, an improved mounting for a loop spreader on a feed carrier, so arranged that maximum accuracy of alignment with the needle is obtained, a novel and improved form of the thread case retainer actuating mechanism, a variable speed looper

actuating mechanism of unique effectiveness and driving and stopping mechanisms providing novel coordination between separate high- and low-speed driving clutches, in combination with a lockout member controlled by 5 braking force applied to a driven shaft in the machine through the action of the low-speed clutch, for holding the low-speed clutch in driving engagement until the speed of rotation of the driven shaft has been reduced to a point where it will coast to a uniform stopping position with certainty. The illustrated stopping mechanism is useful in bringing operating parts of unusually heavy construction reliably to rest in predetermined positions with a minimum of impact. Additional features of the invention, comprising a novel and improved rotary horn mounting, as hereinafter described and claimed, will become apparent from a consideration of the following detailed specification taken in connection with the accompanying drawings, in which

Fig. 30 is a plan view on an enlarged scale of the main sewing shaft and its supporting bearings; and

Fig. 31 is a time chart illustrating the operation of the machine.

The illustrated machine is similar, except as herein-after pointed out, to the lockstitch McKay type, rotary horn shoe sewing machine disclosed in inventors' prior Patent No. 2,670,701, identified above. Referring to Figs. 1 and 7 to 9, inclusive, of the drawings, the machine is provided with stitch forming devices including a straight reciprocating hook needle 2, a straight awl 4, a multiple beak deep-toothed shuttle or looptaker 6, and a rotating needle threading looper in the form of a whirl 8 (see Fig. 14) at the upper end of a work support in the form of a rotary shoe entering horn 10, the horn having a needle receiving opening 11 at its upper end in alignment with the needle. To clamp a shoe on the horn a presser foot 12 having a forked end is secured to the lower end of a vertically reciprocating presser foot bar 14 at the side of the work with the needle, the needle passing through the fork in the foot. To actuate the stitch forming devices the machine has mechanisms driven by a main sewing shaft 15 connected to them.

In order to enable work of greater thickness than heretofore to be operated upon, the needle and awl of the present machine are actuated with a greater reciprocating movement than in prior machines and the lengths of these work penetrating instruments have been correspondingly increased to accommodate essential clearances when work up to a thickness of $1\frac{1}{4}$ inches is being sewn. For actuating the needle and awl, they are secured to the lower ends of separate reciprocating bars 16 and 18 (Fig. 14) retained for sliding movement within a box-like carrier 20, the needle moving laterally in a direction of work feed while in engagement with the work a distance equal to the length of a stitch to impart feeding movement to the work. For a complete disclosure of the mechanism for actuating the needle and awl, reference may be had to the patents above referred to of the present inventors.

The multiple beak loop taker 6 of the present machine is constructed with five double beaks formed in parallel plates 22 (see Fig. 6) and in a toothed gear ring 24 secured together in a unitary structure, the present five-beak shuttle 6 differing from that in the machine of Patent No. 2,670,701, by the provision of an

additional beak. The arrangement of the beaks in the plates 22 and the ring 24 is generally similar to that in the patented machine and each beak is brought successively to a position for reception of a loop of thread drawn through the work by the needle as illustrated in Fig. 7 of the drawings while a loop previously formed and carried about a locking thread case 26 within the shuttle is being contracted. As each loop is carried about the locking thread case the shuttle causes the stitch formed by the preceding loop to be drawn into the work and to be set securely at a predetermined position with the work.

In order to provide thread equal in amount only to that required for each succeeding loop of thread drawn through the work by the needle, a single combined thread controller and pull-off member 28 is provided, as best shown in Fig. 23. The controller is actuated while each loop of thread is being enlarged by the shuttle to draw back a short length of thread from the work so that it will be available as the threaded needle is retracting from the work with the succeeding loop. The drawback action of the thread controller enables only one-half the length of each needle loop to be paid out at the proper time, the other half being withdrawn through the work from the previously formed stitch.

In the machine of Patent No. 2,670,701, the thread controller and pull-off are separate members and accordingly engage the needle thread in different positions causing greater abrasion and wear on a greater length of thread than when the combined controller and pull-off member of the present invention is employed. Besides requiring a greater length of thread for two separate members to operate upon, the two separate members are subject to greater inaccuracies in their movements than a single one. Also, in the prior machine varying qualities of stretch and elastic recovery in the thread occur, because of its greater length than with a single member. In the present machine the combined controller and pull-off member is actuated toward and away from the needle thread running between front or upper and rear or lower thread locks 30 and 32 (see Figs. 21 and 24). To pay out the thread provided by the measuring movements, the thread measuring movements of the controller are adjusted automatically by the thickness of the work operated upon and are timed with relation to the requirements of the other stitch forming devices in a manner to insure satisfactory results. There are two mechanisms for imparting to the improved thread controller the desired movements. These mechanisms are best shown in Figs. 22 and 23 and contain two cam actuated members. One of the mechanisms causes the controller to pull off a length of thread from the supply in accordance with the thickness of the work and the other causes the controller to draw back sufficient thread from the work so that the threaded needle may retract from the work during formation of the succeeding stitch without inducing a sliding movement of the thread engaging the needle hook during the retraction. A proportioning connection is provided between the two cam actuated mechanisms for causing the controller member 28 to draw back a greater amount of thread when operating upon thin work than when operating upon thick work. When work of a maximum thickness of $1\frac{1}{4}$ inches is being sewn there is no thread drawn back by the thread controller, the length of thread measured for each stitch being just sufficient for the full needle retracting stroke. In the illustrated machine the amount of thread drawn back is equal to that required by the threaded needle less the length measured by the pull-off action.

The thread controller and pull-off member 28 comprises a shielded pulley rotatably mounted upon the upper arm of a lever 34 rotatable on a shoulder screw 36. The screw 36 is mounted at one end in a lug 37 (see Figs. 21 and 23) projecting within a cylindrical crown 38 secured at its lower margin by bolts, one of which is

shown at 40 in Fig. 21, to the upper surface of a spacer frame 42. The spacer frame 42 is, in turn, secured at its lower margin by bolts 44 (see Fig. 1) to a hollow subframe 46 which provides a shelf-like projection at the front of a machine head frame for a rotary mounting of the shoe entering horn 10, to be described further. The screw 36 also is supported between its ends by a lug 48 (Fig. 23) projecting inwardly from the crown 38. The thread controller is shown in its maximum thread measuring position in the solid lines of Fig. 21 and in giving-up position in the dot-dash lines of that figure.

The mechanism for causing the controller to draw back and give up thread from the work comprises a lever 50 (see Figs. 15, 22 and 23) having an integral stud 52 passing loosely through a lug 54 extending upwardly from a bottom plate portion of the spacer frame 42. The lever 50 has secured to its intermediate portion a pin 56 on which is rotatably mounted a roll 58 engaging a groove 60 in a cam drum 62. The cam drum 62 is secured to a vertical shaft 64 rotatably mounted at its lower end in a friction reducing bearing 66 secured in the base of the spacer frame and at its upper end the shaft 64 is rotatable in the hub of an eccentric 68 (Fig. 15) fixed in an intermediate partition within the spacer frame, the hub of the eccentric forming a second bearing for the shaft 64. The distal end of the lever 50 has passing through it a pivot 70 which connects it with one end of an arcuate guide bar 72 having an angular lug 74 (Fig. 23) extending from it to form with the bar a confining recess and a support for both ends of the pivot 70. The bar 72 is shaped with a curvature which in one of its positions is concentric to a pin 76 secured in a horizontal arm of the controller lever 34 and between the pin 76 and a stud 78 projecting from a measurement adjusting slider 80 on the guide bar 72 is a link 82 for actuating the controller pull-off member 28. The position of the pin 76 is arranged to be concentric with the bar curvature before the pull-off member 28 is actuated to measure thread.

The mechanism for causing the controller to pull off or measure thread corresponding in amount to that required by the thickness of the work operated upon, comprises a lever 84 (see Figs. 22 and 23) rotating with an integral stud 86 passing loosely through a lug 88 extending upwardly from the bottom plate portion of the spacer frame 42. The lever 84 has secured in its intermediate portion a pin 90 on which is rotatably mounted a roll 92 (Fig. 23) engaging a groove 94 in the cam drum 62. The distal end of the lever 84 is forked and carries a pivot 96 which connects the lever with a link 98 through the upper end of which passes a pin 100 connecting the link with the left end of the arcuate bar 72, which end is opposite to that carrying the pivot 70. To confine the upper end of the link 98 and to support the pivot 100, the guide bar 72 has an angular lug 102 extending from it to provide a bearing for one end of the pivot 100. It is apparent from the construction described that the lengths of movements imparted to the combined thread controller and pull-off member 28 will be proportional to the distances between the adjusting slider 80 which actuates it and the ends of the guide bar 72. The cam grooves 60 and 94 are cut to actuate the bar at different times so that the motion imparted to the guide bar by one of the cam levers 50 or 84 does not affect the motion produced by the other. When the slider is in a position where the stud 78 is in alignment with the pivot 70 in the guide bar there will be no pull-off and measuring movement imparted to the controller member 28, but a maximum extent of drawback and giving-up movement will be imparted thereto. When the slider is in a position where the stud is in alignment with the pin 100 at the other end of the guide bar there will be no drawback or giving-up movement in the thread controller but a maximum extent of pull-off and measuring movement.

To control the position of the slider 80 on the arcuate guide bar 72, the lower end of the link 82 is embraced by the forked end of a connecting link 104 through which the stud 78 also passes. The link 104 enters the space 5 within the forked downwardly extending arm of a bell crank 108 to which it is pivotally connected at 106, the bell crank being mounted for rocking movement on the shoulder screw 36 and being held from lengthwise displacement by the head of that screw. Another forked arm of the bell crank 108 embraces the upper end of a vertical link 110 which surrounds a pin 112 carried by the bell crank. The lower end of the link 110 has passing loosely through it a pivot 114 secured to an arm of a horizontal lever 116. The lever 116 is fulcrumed on a horizontal shaft 118 secured in the subframe 46 and another arm of the lever 116 has projecting from it a pivot 120 connecting it with the lower end of a rod 122 which passes upwardly into the machine head frame, indicated at 124 (Fig. 1), in which the needle, awl, shuttle and a main sewing shaft are supported. The upper end of the rod 122 is connected to a mechanical relay arranged to be adjusted by the thickness of the work being operated upon, as will be described.

The front and rear thread locks 30 and 32 are actuated alternately to clamp and release the thread, the front lock 30 (see Fig. 21) between the controller and the work clamping the thread during the thread measuring movement of the controller and the rear lock 32 clamping the thread during the pull back and giving-up movements 15 of the controller. For actuating the thread locks to lock or release the thread, thread engaging shoes 126 and 128 clamp the thread against stationary anvil blocks comprising the locks 30 and 32. Each clamp shoe is mounted for limited rocking movement on a pin 130 having its ends secured in spaced lugs on the respective shoes. Between the lugs and surrounding each pin 130 is an enlargement on a carrier arm 132 or 134, the arm 132 acting as a mounting for the shoe 126 and the arm 134 for the shoe 128. Both carrier arms 132 and 134 are 20 mounted for rocking movement on a common stud 136, the carrier arms both being forked to provide spaced bearings through which the stud 136 passes, and the ends of the stud being secured at opposite ends in the cylindrical crown 38 forming a part of the machine frame. 25 Between the spaced bearings of both the arms 132 and 134 is a lock operating block 138 (see also Fig. 24) having one end rotatable on the stud 136 and being provided with a pair of fingers 139 between which are disposed two projections 140, one on each of the arms 132 and 134. The projection on the arm 132 is normally held against the uppermost finger of the block 138, and the projection on the arm 134 is normally held against the lowermost finger on the block 138 by a pair of coil springs 141 enclosed in hollow lugs on the respective arms 30 and compressed between the block 138 and a pair of adjusting screws 142 threaded into the lugs on the arms. The springs 141 provide yielding connections between the block 138 and the respective arms 132 and 134, so that as the block swings about the axis of the stud 136 the front thread lock 30 or the rear thread lock 32 is actuated selectively to clamp the thread with a yielding pressure. When one lock is actuated to clamp the thread the other lock is actuated to release it through the engagement of a finger on the block 138 and a projection from the arm 132 or 134. The fingers on the block 138 and the projections on the arms 132 and 134 are so arranged that both locks are actuated to clamp the thread before either releases it, so that there is an overlapping clamping action between them. 35

To supply thread to the locks and the pull-off pulley, a rotatable thread supply device 144 (see Fig. 1) similar to that disclosed in United States Letters Patent No. 1,909,157, granted May 16, 1933, on application of Erastus E. Winkley, is mounted on the right side of the subframe 46. From the thread supply device 144, the 40

needle thread indicated at 145, extends downwardly and is carried about a pulley 146 rotatable on a bracket 148 secured to the subframe, through an opening 150 in the subframe, to a pulley 152 on a wax pot 154 and downwardly and upwardly through the wax pot and over a pulley 156 in the spacer frame 42. From the pulley 156 the thread passes at an upward inclination to the vertical and under a roll 158 (see Fig. 23), and vertically through the rear thread lock 32. From the rear thread lock 32 the thread passes over a pulley 160 (Fig. 21) rotatable on a projection from the cylindrical crown 38 horizontally to the pull-off pulley member 28 and in the opposite direction to a pulley 162 mounted for rotation on a projection from the crown 38. From the pulley 162 the thread extends upwardly through the front lock 30 and through the axis of rotation of the horn 10, in accordance with the usual practice in a machine utilizing a rotary horn. The roll 158 is mounted for rotation in a slot formed in a rib projecting from the hub of the controller lever 34. To prevent escape of the thread from engagement with the roll 158, the rib of the controller lever 34 has mounted on it a spring clip 163 which closes the slot in which the roll 158 is mounted.

For actuating the thread lock operating block 138, a lug projecting from the block has passing through it a pin 164 (see Figs. 21 and 24) also passing through the forked upper end of a link 166. The link 166 enters the lower end of the crown 38 from the frame of the machine along with other connections for actuating the thread controller 28. The forked lower end of the link 166 is pivotally connected by a pin 168 to the outer end of a lever 170 which has rotatably mounted on its end opposite the pin 168 a cam roll 172 (Fig. 24). The cam roll 172 projects into a cam groove of a U-shaped lever 174. The lever 174, during normal sewing operations, is stationary so that the lever 170 moves about the center of the roll 172 as a fulcrum. Between its ends the lever 170 has passing loosely through it a pin 176 secured to an intermediate portion of an offset lever 178 having an integral stud 180 rotatable in a lug 182 (Figs. 22 and 24) on the spacer frame 42. The end of the lever 178 remote from the stud 180 carries a roll 184 entering a groove 186 in the cam drum 62. Movement of the cam roll 184 by the cam groove 186 causes the lever 170 to move the thread lock operating block 138 in the proper relationship with the thread drawback, giving-up and measuring movements of the controller. When the machine is brought to rest the lever 174 is shifted to the position of Fig. 24 by swinging it about a pair of vertical screw studs 188 on which it is rotatably mounted to change the timing of the thread lock operating movements of the block 138 in a manner to be described, so that when a sewed work piece is withdrawn from the machine the thread measured by the controller 28 will not be withdrawn with the work piece but will be available in starting a new seam to ensure proper formation of the first stitch in the seam. For this purpose the cam groove in the lever 174 when shifted, moves the roll 172 downwardly raising the lock operating block 138 to close the front lock 30 between the controller and the work, thus locking the measured thread against withdrawal from the machine.

To enable convenient thread withdrawal from the machine by the operator while the machine is stopped so that a fresh length of thread will be available or for other purposes, the front thread lock 30 is arranged for temporary operation to release the thread. The stud 136 on which the upper thread lock arm 132 is rotatable has loosely mounted on its left end a lever 190 (see Fig. 24) provided with an upwardly extending arm movable against a pin 192 projecting laterally from the lock operating arm 132. A horizontally forked arm of the lever 190 has passing through its fork and the upper end of a rod 194 disposed between its fork portions a pivot pin 196. The lower end of the rod 194 has secured

to it a spool 198 between the flanges of which enter spaced projections on an arm 200 secured to a rockshaft 202. The rockshaft 202 is rotatable in the free end of the subframe 46 and has provided at its left end, which projects from the subframe, an operating handle 204 projecting into a position conveniently accessible to the machine operator. By pressing the handle 204 rearwardly the operator rocks the shaft 202, raising the rod 194 which forces the arm 132 against the pressure of the upper spring 141 to open the front lock 30. As soon as the handle 204 is released, the front lock 30 closes and the weight of the rod 194 causes the lever 190 to disengage the pin 192.

To change the timing of the thread lock operating movements of the block 138, the cam lever 174 has a slotted arm through the slot of which a shouldered bolt 206 passes (see Fig. 24). The enlarged upper end of the bolt 206 also passes loosely through the end of an arm 208 secured to a vertical shaft 210 rotatable in the spacer frame 42. The shaft 210 has secured to it at its lower end an arm 212 engaged by a horizontal push rod 214 slidingly mounted in the subframe 46. When the machine is brought to rest the push rod 214 is pressed forwardly causing the cam lever 178 to actuate the lock operating block 138 in the desired manner. To return the cam lever 170 from stopped position to a position assumed when the machine is in normal sewing operations, the arm 212 has a spring 218 stretched between it and a pin 216 on the subframe. The movement of the cam lever 170 to the position of Fig. 24 causes the upper thread lock to be closed and the lower thread lock to be opened as the machine is coming to rest. Retiming of the thread locks in this manner is independent of the position of the cam roll 184. In order to prevent retention of the cam lever 174 in its stopped position so that the front thread lock will be held closed and the lower one held open during sewing operations the cam lever 174 carries a roll 220 rotating on a vertical axis and engaging a circumferential cam surface 222 on the drum 62. The surface 222 has a cutaway portion which is entered by the roll 220 when the lever 174 is moved as the machine is brought to rest. Upon starting the machine the surface 222 of the drum 62 forces the roll 220 out from the cutaway portion and restores the cam lever 174 to its sewing position.

For actuating the push rod 214 to change the timing of the thread locks at the end of a sewing operation and for performing certain other auxiliary operations, such as to raise the presser foot from engagement with the work, the machine is equipped with driving and stopping mechanisms to be described more fully hereinafter. The driving and stopping mechanisms are enclosed within the subframe 46 of the machine and are quickly removable for replacement of parts, adjustments and convenience in servicing. The driving and stopping mechanisms also are arranged to actuate a lubricating system for the machine whereby oil is distributed to the moving parts each time the machine is brought to rest and again restarted.

The presser foot 12 is actuated to clamp, to release and to be raised from engagement with the work a uniform distance during each sewing cycle of the machine, regardless of the thickness of the work operated upon, by mechanism driven from the main sewing shaft. Also associated with the presser foot is a work caliper feeler 224 (Fig. 7), connected to the thread measuring mechanism to adjust automatically the amount of thread measured by that mechanism as the work varies in thickness. The feeler 224 has connected with it the mechanical relay for transmitting the adjusting movement to the thread measuring mechanism after the presser foot is locked securely in work clamping position. The feeler is mounted for movement with the presser foot so that adjustment of the thread measuring mechanism is controlled in part by the presser foot and in part by the

caliper feeler. The presser foot and its actuating mechanism, the feeler and relay are best shown in Figs. 1, 2, 7 to 9, inclusive, and 21 and 22.

Referring more particularly to Figs. 6 to 9, inclusive, the mechanism for actuating the presser foot to clamp and release the work and to be lifted from engagement with the work is generally similar to that disclosed in inventors' prior Patent No. 2,670,701. Provision is also made to lift the presser foot manually from the work. To actuate the presser foot the main sewing shaft 15 (see Fig. 30) carries a single cam disk 226, shown in Fig. 10, in two parts broken along a plane intersecting the sewing shaft at right angles and the parts illustrated in separated relation for the sake of convenience. At either side of the cam disk is cut a groove engaged by one of a pair of cam rolls 228 and 230. The cam rolls 228 and 230 are rotatably mounted on two operating levers 232 and 234, respectively, fulcrumed on a common shaft 236 having its ends rotatably mounted in bearings projecting from the head frame 124. The two levers 232 and 234 are operatively connected to reciprocate the presser foot bar 14 and to lock and unlock a presser foot lock, respectively. The lifting connections between the presser foot bar and the lever 232 comprise a horizontal rockshaft 238 mounted for rotation in bearings on the head frame and provided with a presser foot lifting arm 240 at its forward end connected through a link 242 to a block 244, secured to the presser foot bar 14. The hub of the arm 240 surrounds the rockshaft 238 and is formed with a split clamp by which it is fixed to a sleeve 246 rotatably mounted on the rockshaft. The sleeve 246 also has projecting from it an integral arm 248 connected to the lower end of a link 250, the upper end of which is pivotally connected at a point 252 midway between the ends of a floating lever 254. The floating lever also has the presser foot lock connected to one point along its length near one end and the operating lever 232 connected to another point near the other end.

To connect the presser foot lock with the floating lever 254, the floating lever is forked and surrounds a central wedge 256 and has at opposite sides of it a pair of wedges 258 through all of which passes a connecting pin 260. The wedges 256 and 258 comprise the presser foot lock which is constructed in a manner similar to that of the lock disclosed in United States Letters Patent No. 2,054,078 granted September 15, 1936, upon application of Gouldbourn et al. Between the wedge 256 and one of the wedges 258 is interposed a zig-zag series of rolls 262 and between the wedge 256 and the other wedge 258 is interposed a spacing block 264 held against vertical motion but arranged for free horizontal motion. To lock and unlock the presser foot bar the uppermost roll of the series is engaged by an arm of an offset lever 266 rotatable on the head frame. The offset lever is pressed yieldingly against the uppermost roll to lock the presser foot. Another arm of the lever is disposed beneath one arm of the lock actuating lever 234. During sewing operations the cam lever 234 unlocks the presser foot to enable the presser foot to adjust its position with varying thicknesses of work as the sewing progresses.

The point of connection of the floating lever 254 with the presser foot lifting lever 232 is defined by a pin 267 passing through the floating lever and the bifurcated upper end of a link 268. The link 268 has projecting from it a pivot 269 passing loosely through a block 270 slidably mounted within an arcuate slot in one of the arms of the presser foot lifting lever 232. The lower end of the link 268 is pivotally connected by a screw 272 with a link 274, in turn pivotally connected by a screw 276 with a downwardly extending arm 278 on a shaft 279. As the main sewing shaft 15 is rotated the cam lever 232 is oscillated to raise and lower the link 268, the floating lever 254 connected to it acting about the lock pivot pin 260 as a fulcrum to rock the sleeve 246 and lift and lower the

presser foot out of and into engagement with the work through the arm 240 and the link 242.

To enable the presser foot to be unlocked and lifted manually from engagement with the work, the shaft 238 inside the sleeve 246 has mounted for free rotation on it near its forward end a handle lever 280. At its rearward end the shaft 238 has keyed to it with freedom for sliding movement a spool 282 provided with projecting hubs. One hub is cut with a series of three steps, engageable 10 slidingly with a right angle corner on an unlocking sleeve 284 mounted for free rotation on the rockshaft 238. The unlocking sleeve has projecting from it a segmental cam 286 located for engagement with one arm of a lever 288 rotatable on a fixed stud 290. Another arm of the lever 288 has pivotally connected to it the lower end of a vertical link 292, the upper end of which is connected to one arm of the offset lever 266. To press the roll engaging arm of the offset lever 266 yieldingly against the uppermost roll 262, a lug on the lever 288 supports 15 one end of a spring 294 compressed between the lug and a fixed portion of the machine frame. The spring 294, therefore, serves to hold the presser foot lock in locked condition except when unlocked by the cam lever 234. When the handle lever 280 is rotated in a clockwise 20 direction, as viewed in Fig. 10, an offset arm thereon moves into engagement with a projection on a collar 296 pinned to the forward end of the shaft 238. Continued rotation of the handle lever rocks the spool 282 and causes the unlocking sleeve 284 to be rotated, the lever 288 moving in the proper direction to disengage the offset lever 266 from the uppermost roll 262, thus unlocking 25 the presser foot lock. Further rotation in a clockwise direction of the handle lever 280 brings a segmental projection 297 on the unlocking sleeve 284 into engagement with a similar projection 298 on the sleeve 246 to which is clamped the presser foot lifting arm 240. Additional rotation of the handle lever thereafter lifts the presser foot from the work to free the work for removal 30 or adjustment of its position with relation to the stitch-forming devices. The projection 297 extends about the shaft 238 through an angular extent of 90°, whereas the projection 298 extends through an angle of 180°, leaving an angle of 90° for free relative movement between the 35 unlocking sleeve 284 and the sleeve 246.

The free relative movement, between the sleeves 284 and 246, is provided to enable the presser foot to be unlocked and then to be raised from engagement with the work in successive steps. All of the free relative movement is necessary in order to ensure unlocking when the presser foot engages the thinnest work for which the machine is intended to operate. As the work increases in thickness it is desirable to limit the amount of relative movement between the sleeves 284 and 246.

To enable the greatest relative movement between the sleeves 284 and 246 when work of minimum thickness is being operated upon, the spool 282 is moved along the shaft 238 to bring its lowest step into engagement with the right angle corner on the rearward end of the sleeve 284. As shown in Fig. 10, an intermediate step engages 55 the corner of the sleeve 284 so as to adjust the relative movement between the sleeves 284 and 246 for medium thickness work. When the highest step on the spool is brought into engagement with the corner of the sleeve 284, the presser foot will be unlocked and raised in proper sequence from work of maximum thickness. Thus, the presser foot lock is unlocked earlier with thin work and later with thick work as the rockshaft 238 is rocked.

To shift the position of the spool 282 along the shaft 238 so as to bring different steps on the spool into engagement with the corner of the sleeve 284, the space between the flanges of the spool 282 is entered by the ends of a fork 299 secured to a horizontal shaft 300 rotatably mounted in the right side wall of the head frame 124. 60 Outside the head frame the shaft 300 has integrally con-

ected to it an adjusting arm 302 carrying a spring pressed plunger 304 arranged to enter one of a series of openings 306 formed in a boss on the head frame. Retraction of the plunger 304 from the boss enables the spool 282 to be shifted to one of three positions depending upon the thickness of the work intended to be operated upon.

For the purpose of adjusting the distance by which the presser foot is lifted automatically from clamping engagement with the work during sewing operations, means are provided for varying the effective length of the slotted arm on the operating lever 232. To this end the shaft 279 extends through the front wall of the head frame 124 and has integrally connected with it an arcuately slotted adjusting segment 308 arranged to swing along the surface of a pad on the front of the head frame. Any swinging movement imparted to the segment 308 rocks the shaft 279 and the arm 278 to impart movement to the lower end of the link 266 through the link 274, causing the block 270 to shift its position in the slot of the presser foot operating and lifting lever 232. For securing the segment 308 in the position to which it is adjusted, the slot in the segment has passing through it a clamp screw 310 threaded into the pad on the head frame. The segment 308 being exposed on the outer surface of the head frame is readily accessible for actuation to increase or decrease the lifting movement imparted to the presser foot by the lever 232, the slot in the lever and the block 270 serving as a simple and effective length varying means for the presser foot lifting and lowering mechanism.

At certain times in each sewing cycle, particularly at the time in which the threaded needle starts to withdraw its loop of thread from the work it is desirable to avoid any possibility of work displacement. Accordingly, in the illustrated machine a second lock is connected to the presser foot for resisting lifting movement of the presser foot, particularly while the threaded needle is withdrawing from the work.

The second presser foot lock comprises a vertical flange on the block 244 provided with teeth forming a ratchet 312 cooperating with a set of four pawls 314, mounted for swinging movement on a pin 316 supported at its ends in a bracket 318 secured by screws 320 to the head frame (see Figs. 10 and 11). The pawls are pressed yieldingly against the ratchet 312 by individual springs 322 mounted in openings in the bracket 318 and engaging alined openings in the pawls. To disengage the pawls from the ratchet, a pair of links 324 are mounted for swinging movement on the pin 316, one link being mounted at either side of the set of pawls between the pawls and flange portions of the bracket 318. The links 324 have passing through them a stud 326 (see Figs. 10, 11 and 14) being held from displacement from the links by cotters, one of which is shown at 328. The pin 316 also is held in place by similar cotters 330. The stud 326 has projecting rearwardly of the rearmost link 324 a portion carrying a roll 332 pressed yieldingly against a cam surface on a lever 333. To press the roll against the cam surface of lever 333, one of the links 324 is engaged by a spring 334 compressed between the link and the bracket 318. The lever 333 is operated in proper timed relation from the sewing shaft to cause the stud 326 to disengage the pawls from the ratchet 312 before the presser foot is lifted from the work in each sewing cycle.

The lever 333 which operates the presser foot ratchet lock is a part of a mechanism which imparts the feeding movement to the needle 2. This mechanism acts to shift the needle and awl carrier 20 in the direction of work feed while the needle is in engagement with the work, returning the carrier when the needle is disengaged from the work. For this purpose the carrier 20 is mounted for feeding movement on a pair of horizontal bars 335, shown in Fig. 14, and is pivotally con-

nected through a link 336 to a central pivot 337 of a pair of links 338 and 339. The link 338 is pivotally connected to an arm 340 secured to a shaft 341 rotatably mounted in a projection from the head frame 124. The shaft 341 has secured to it a cam actuated arm 342 and is loosely surrounded by the hub of a second cam actuated arm 343 to which is connected the lever 333 formed with the presser foot ratchet actuating cam surface. For the purpose of changing the length of feeding movement imparted to the feed carrier 20, a downwardly projecting arm of the lever 333 is pivotally connected to the link 339 through an adjustable bolt and slot connection. For a better understanding of the mechanism for actuating the feed carrier, reference may be had to inventors' prior application Serial No. 349,872, above noted.

To lift the presser foot from engagement with the work at the end of a seam, the rearward end of the rock-shaft 238 has secured to it a bell crank 344 (Fig. 10), one arm of which is pivotally connected to a downwardly extending link 345 actuated by the driving and stopping mechanisms in a manner to be described. At the end of a sewing operation the link 345 is moved downwardly, rocking the shaft 238 in the proper direction to lift the presser foot to an elevated position where it is held by the driving and stopping mechanisms until the machine is restarted. The timing of the locking pawls 314 is such that they are disengaged from their ratchet 312 and so permit the presser foot to be lifted in the stopped position of the machine.

With certain types of work, particularly when it is necessary to cut a stitch receiving groove in the work by means of a knife attached to the presser foot, it is the practice to relieve the clamping pressure on the presser foot without lifting it from engagement with the work as the work is fed. To enable the presser foot to remain in engagement with a shoe on the horn even though the presser foot bar 14 is lifted during sewing operations, there is provided a yielding connection between the presser foot and its bar. The yielding connection includes a sleeve 346 (see Fig. 11) surrounding a reduced lower end of the presser foot bar. The bar is provided with a shoulder within the sleeve, between which shoulder and the lower end of the sleeve a coil spring 347 is compressed. When the presser foot bar is lowered by its actuating mechanism to clamp a shoe on the horn, the spring 347 yields until the upper end of the sleeve engages the block 244. When the bar 14 is lifted the presser foot remains in engagement with the shoe throughout the length of relative movement between the sleeve and the bar. To prevent escape of the sleeve from the bar the lower end of the bar is threaded and carries a pair of check nuts 348 which may be adjusted to cause the presser foot to lift from engagement with the work in the regular manner or, alternatively, to remain yieldingly in engagement therewith.

For transferring each loop of thread drawn through the work by the needle to the looptaker 6, a convenient form of loop spreader is provided comprising a curved rod 349 (see Fig. 14) secured at one end in a socket provided in a crossbar 350 and at its other end formed with a notch to support one side of each needle loop in the path of a looptaker beak. The crossbar 350 is fixed at its ends in a pair of parallel arms 352 and 354. The arm 354 has pinned to it a stud 356 rotatably mounted in the needle and awl carrier 20. The arm 352 is a part of an actuating lever for the loop spreader and has pinned to it a stud 358 also rotatably mounted in the carrier 20, the loop spreader arms being mounted on the carrier to cause it to move toward and from the path of the needle into engagement with each needle loop for accurate presentation of the loop to the loop taker. Inasmuch as the needle feeds the work while in engagement therewith and the loop spreader moves with the needle during its work feeding and back feeding movements, no special

provision is necessary to maintain the spreader in alignment with the needle as a result of its feeding and back feeding movements.

To actuate the loop spreader the lever formed by the arm 352 carries a ball-headed stud 360 surrounded at its ball end by a socket at the lower end of a vertical link 362. At the upper end of the link 362 is a similar socket surrounding the ball end of a stud 364 secured in an arm 366 made fast to the forward end of the shaft 236. At its rearward end the shaft 236 has secured to it an arm 368 (Figs. 14 and 30) carrying a roll 370 engaging a groove in a cam disk 372.

To bring the presser foot yieldingly into engagement with the work before the application of a work clamping pressure and before the adjustment of the thread measuring mechanism for the thread controller, the upper end of the presser foot bar 14 is surrounded by a threaded tube 374, best shown in Fig. 10. The threaded portion of the tube engages a threaded bearing in a bracket 376 (see also Fig. 2), secured to the upper portion of the head frame 124. Within the tube is mounted a coil spring 378 acting at its lower end against the upper end of the presser foot bar 14 and at its upper end on a button 380 pinned to the upper end of the tube 374 and provided with a knurled edge to facilitate manual rotation of the tube. By rotating the tube, compression of the spring 378 may be increased or decreased in accordance with the nature of the work operated upon.

The work caliper feeler 224 is mounted for separate yielding movement relative to the presser foot 12. To enable the feeler to register the thickness of the work at the point where a stitch is being formed it is located to engage the work to the rear of the line of a seam being inserted and along the line of the seam in advance of the point of needle operation. The upper end of the feeler is clamped within a lug on a slide 382 (Figs. 10 and 11) guided on the presser foot bar for vertical movement relative to the presser foot. The slide 382 has two bearing portions surrounding the presser foot bar, one above the other. The lowermost bearing portion of the slide is formed with three arms, one of which supports the feeler 224, another of which forms a strut connected with the uppermost bearing portion and a third of which provides a guide bearing. At opposite sides of the presser foot bar the first and third mentioned arms projecting from the lower bearing portion are perforated and receive in sliding engagement therewith a pair of vertical pins 384 secured by set screws 386 in the head frame 124. The pins 384 prevent rotation of the feeler slide while enabling the feeler to move freely relatively to the presser foot. The pins 384 also pass through close fitting openings in a crosshead at the lower end of the sleeve 346 to prevent angular displacement of the presser foot which is secured to the lower end of the sleeve. To secure the presser foot 12 to the lower end of the sleeve 346, the presser foot has an upstanding slotted flange through the slot of which passes a clamp bolt 388, also entering an opening in the crosshead portion of the sleeve. The presser foot also has a clearance opening for the check nuts 348 and one of the pins 384. To limit the relative movement between the slide 382 and the presser foot in a vertical direction the sleeve 346 has clamped to it a collar 390, between which and the crosshead the slide is confined. The position of the collar is adjusted to enable the feeler 224 to project beyond the lower work-engaging surface of the presser foot or to be retracted from the level of the work-engaging surface of the foot.

In providing the illustrated machine with accommodations for sewing work of 1 1/4-inch thickness, it is possible to sew shoes of a different character than have been operated upon heretofore. One purpose for which the illustrated machine is intended is inserting a continuous seam throughout the marginal portions of a wedge heel shoe, wherein the thickness of the material operated upon

changes rapidly from the sole along the forepart to the full thickness of the heel within a relatively few stitches. With the use of prior needle thread measuring mechanisms, particularly when a presser foot alone is arranged to caliper the thickness of the work, difficulty is encountered by the provision of too short a length of measured thread as the thickness of the work is decreasing or too long a length of measured thread when the thickness is increasing. For this reason the caliper action 10 of the illustrated machine is accomplished by locating the feeler along the line of a seam being inserted, at least a full stitch in advance of the point where each stitch is set in the work. Such arrangement of the feeler enables the caliper action to be performed at that point in the work where a particular length of thread measured will be consumed in each stitch being formed. As illustrated in Fig. 7, the length of the work-engaging surface of the presser foot along the line of a seam is indicated by a distance 392. The area of the work-engaging surface along this distance is located directly above and cooperates with the upper work-engaging surface on the horn. If the surface of the presser foot is used to caliper the work it will register an increase of thickness too soon and a decrease in thickness too late as 15 will be apparent from a comparison of Figs. 8 and 9. Consequently, if the position of the presser foot on the work is relied upon to adjust the thread measuring mechanism, improper amounts of thread will be measured.

During operation of the illustrated machine the needle 30 passes through the forked end of the presser foot in advance of the position of the feeler 224 as the needle penetrates the work and enters the opening 11 in the horn. After the thread is laid in the hook of the needle, it withdraws until the threaded hook is clear of the horn 35 and is located between the upper and lower surfaces of the work. The work is then fed a stitch length by lateral movement of the needle to a position beyond the feeler, the presser foot being raised at this time. During continued operation of the machine the threaded needle 40 withdraws completely from the work and the stitch is set beyond the feeler. Before each stitch is set the presser foot is actuated into clamping engagement with the work and the feeler 224 accomplishes a caliper action at a new position on the work more than a stitch length in advance of the point where the stitch is set. It thus provides a measurement of the work thickness somewhere between the second and third stitches in advance of the point where the last stitch is set. In this way, it is possible to transfer uniformly the measurement caliper by the feeler through the mechanical relay to the thread measuring mechanism before the thread measured for a particular stitch is consumed.

To enable the feeler to caliper work of increasing as well as decreasing thickness with equal effectiveness, it 55 is arranged to engage the work at least a full stitch in advance of the point of needle operation, and also to the rear of the seam line, so that if the presser foot is raised by a distance 394 (Fig. 8) through the engagement of its heel portion with work of increasing thickness, the feeler projects beyond the work engaging surface of the presser foot. To register a decreasing thickness of the work the feeler is retractable, as by a distance 395 (Fig. 9) during the work clamping action of the presser foot to a position above the work engaging surface thereof. When the thickness of the work remains the same for several stitches the lower end of the feeler is held flush with the work-engaging surface of the presser foot (Fig. 7), and no movement relative to the presser foot is imparted to the slider 80 of the thread 60 measuring mechanism.

The arrangement of the feeler 224 and its carrier 382 on the presser foot bar enables the presser foot to be actuated in a conventional manner in clamping and releasing the work to cause the feeler first to assume a rough 65 measurement of the work thickness. The presser foot 70

after clamping the work is locked from disengagement thereof and the feeler then accurately calipers the work thickness. The advantage of this arrangement is that the clamping action of the presser foot may indent the work more or less along its work engaging surface, whereas the pressure on the work engaging end of the feeler is relatively light and provides a more accurate measurement for controlling the length of thread to be used, the relative movement between the foot and the feeler being limited to register only the maximum difference in positions assumed for the range of work intended to be sewn.

To enable the feeler 224 to adjust itself readily for changes in thickness of the work with an accurate caliper ing action the slide 382 (Figs. 10 and 11) is actuated downwardly during each stitching cycle with the presser foot until it bears yieldingly against the work and any change in the thickness of the work thereafter causes an adjustment to be registered by a change in position of the adjusting slider 80 in the mechanism for actuating the thread measuring controller 28. The change in the position of the adjusting slider 80 is produced by a simple direct movement which differs from that taking place in the machine of inventors' Patent No. 2,670,701, in which a mechanical relay is provided with a driven member acting with a complete oscillation during each sewing cycle even though no change of adjustment is required. The connection between the relay of the prior patent and the adjusting member for the pull-off arm is relatively long and heavy so that the oscillation of the driven member at high sewing speeds may cause considerable reaction both on the relay and on the presser foot which causes the adjustment. In the present machine where the relay is controlled by a feeler such oscillations would produce undesirable irregularities in thread measurements, the feeler not having sufficient area of contact with the work to prevent indentation of the work and faulty caliper ing action on the work where heavy reactions occur. With the present machine, however, the driven member of the mechanical relay causes no movement whatever to be imparted to the adjusting member of the thread measuring mechanism when work of uniform thickness is being operated upon. When a change in thickness of the work does occur, a relatively simple correcting adjustment is made in the position of the slider 80 to bring it into proper position, the actual adjusting movement being so small that reaction produced in the mechanical relay will not affect the feeler adversely.

The mechanical relay of the illustrated machine is best shown in Figs. 2, 10, 25 and 26. To connect the feeler slide 382 with the mechanical relay, the slide is pivotally connected to the lower end of a link 396, the upper end of which is similarly connected to an arm 398 secured to a stud 400 rotatably mounted in a projection from the head frame 124. The stud 400 has secured to one end opposite that which carries the arm 398, an arm 402 pivotally connected through a rod 404 with an arm 406 secured to a shaft 408 rotatably mounted in a lug of a relay bracket 410. The shaft 408 has integrally connected with it a controlling guide arm 412 having a groove extending lengthwise along it within which is fitted a roll 414. The roll 414 comprises a part of a relay actuator including a pin 416 passing through the lower end of a link 418. At the end of the pin 416 opposite the roll 414 is a second roll 420 mounted for sliding movement in a groove of a driven arm 422 having an integral shaft 424 mounted in alignment with the shaft 408 in the relay bracket. The arrangement is such that if the actuator link 418 is raised to a position where the pin 416 is aligned with the shafts 408 and 424, the controlling member 412 is free to swing relatively to the grooved driven arm 422. If the actuator link and the rolls 414 and 420 are moved downwardly and the controlling member 412 is held stationary, the

roll 420 will move the driven arm 422 into the same angular position about its stud as that occupied by the controlling member. Accordingly, when the pin 416 is in alignment with the shaft 408, the feeler may move without restriction into yielding engagement with the surface of the work. The force of a light spring 426 (see Figs. 10 and 11) connected between pins on the carrier 382 and the crosshead of the presser foot sleeve 346 is sufficient to maintain the yielding engagement of the feeler with the work during the action of the mechanical relay, the movement imparted to the slider 80 being reduced to a minimum.

To raise or lower the relay actuator link 418, its upper end is pivotally connected to an arm 428 secured to a rockshaft 430 mounted for rotation in the relay bracket 410. At one end of the rockshaft 430 is secured an arm 432 carrying a roll 434 engaging a groove in a cam 436 secured to the main sewing shaft 15.

The grooved driven arm 422 of the mechanical relay is connected to the thread measurement adjusting slider 80 through the rod 122, the upper end of which is pivotally connected to an arm 438 fixed to a stud 440 rotatably mounted in a lug on the head frame 124 and provided with a slotted arm 442 fixed to it. In the slot of the arm 442 is clamped a bolt 444 forming a pivotal connection with an adjustable link 446 surrounding a pin 448 (Fig. 26) on the driven arm 422. The bolt 444 may be loosened and its position shifted in the slot of the arm 442 to vary the motion transferred from the relay to the slider 80 of the thread measuring mechanism. The motion imparted to the relay actuating link 418 is such that the slider 80 is readjusted only after the presser foot is locked in engagement with the work and the feeler 224 has had an ample opportunity to complete its caliper ing action on the work. Thus, the possibility of reaction in the connections between the relay and the measurement adjusting slider 80 is minimized.

Referring to Figs. 5, 6, and 7, the arrangement of the shuttle or loop taker 6 is generally similar to that disclosed in inventors' Patent No. 2,670,701, the shuttle being located at the side of the work with the needle and arranged to take a loop of thread from the needle with one of its beaks while another beak retains control of the previously formed loop of needle thread. The shuttle is gear driven from the sewing shaft 15 with a driving ratio corresponding to the number of beaks on the shuttle less one to the whole number of beaks. The driving ratio of the gear drive connecting the shuttle with the sewing shaft is $\frac{1}{5}$ to 1, there being five beaks, and the throat of each beak is formed with a deep recess between two adjacent teeth on the shuttle gear ring 24. Within the shuttle is rotatably mounted the locking thread case 26 arranged to be held from rotation with the shuttle by a pair of retainer members 450 and 452 formed with conical nibs at their ends engaging perforations 454 and 456 in an outer flange on the thread case. To provide support for the locking thread supply bobbin, indicated at 458 (Figs. 5 and 7), the center of the thread case has projecting from it a ferrule 460 fitting within the hub of the bobbin.

As in Patent No. 2,670,701, the illustrated shuttle includes a hollow gear ring 24 meshing with teeth on a driver gear 462. The driver gear 462 is secured to a flange at the forward end of a driver shaft 464 carrying at its rearward end a driven arm 466 of a drag link connection, including a drag link 468 and a driving crank 470 secured to a constant speed shaft 472 rotatably mounted in the head frame. The constant speed shaft 472 is connected to the sewing shaft 15 through a pair of meshing spur gears 474, each secured to one of the shafts.

In the machine of inventors' Patent No. 2,670,701, thread case retaining members are provided secured to levers fulcrumed on a pin passing in front of the area of intermeshing engagement between the driver gear and

the gear ring in the shuttle. As a consequence, the area in front of the intermeshing position of the gears is obstructed, causing inconvenience in removal of thread ends thrown off by the shuttle and nipped within the mesh of the driver gear and the gear ring. Furthermore, the driver gear of the patented machine is provided with face cams for actuating the retainer members alternately toward and from engagement with the thread case. If an attempt is made to change the position of the driver gear on the driver shaft so as to accelerate or retard the entry of a shuttle beak into a needle loop, the times of operation of the thread case retainer members will be changed correspondingly. Change in the times of operation of the thread case retainer members may result in difficulty from improper release of the needle loops from the shuttle. To avoid these difficulties the mechanisms for actuating the thread case retainer members in the illustrated machine have been modified to provide a space surrounding the driver gear, which space is clear of obstruction from the front of the machine, affording convenient removal of thread ends nipped by the mesh of the driver gear and the gear ring. Also, a cam drum for the retainer member actuating mechanisms has been secured to the driver gear shaft independently of the driver gear so that the position of the driver gear may be shifted with respect to its shaft and the timing of the shuttle correspondingly adjusted without changing the times of operation for the thread case retainer members.

To provide space surrounding the shuttle driver gear and, particularly, directly in front of the area in the machine between the driver gear and the shuttle, the retainer members 450 and 452 are secured by split hub portions and clamp screws 476 to a pair of parallel shafts 478 and 480 rotatably mounted in bearings 482 screwed to a shuttle raceway and drive enclosing frame 484. For mounting the shuttle driver shaft 464 on the head frame the rearward end of the shaft engages a bearing in the frame and the forward end of the shaft has a disk-like head to the rear of which is located a bearing supported by a circular plate 486 bolted to the head frame 124. The drive enclosing frame 484 is in turn secured to the plate 486.

To actuate the retainer supporting shafts 478 and 480, their upper ends carry a pair of similar gear segments 488 and 490 engaging teeth on a pair of parallel rack bars 492 and 494 guided for sliding movement in the bearing supporting plate 486. The rack bars extend through the plate and carry at their rearward ends a pair of rolls 496 and 498 engaging grooves in a cam drum 500 secured to the shuttle driver shaft 464. At the front ends of the rack bars 492 and 494 the shafts 478 and 480 lie outside the diameter of the driver gear 462 and of the shuttle itself, there being no obstruction in front of either. The rack bars move in the plate 486 in a direction parallel to the axis of the shuttle driver gear shaft 464, so that they never move within the diameter of the driver gear.

To provide adjustment for the timing of the shuttle without producing a corresponding change in timing of the thread case retainer members, the shuttle driver gear 462 is secured to the shuttle driver shaft by three clamp screws 502 passing through arcuate slots in the driver gear and extending into engagement with threaded openings in the disk-like head of the driver shaft 464. The center of the driver gear also is bored to receive a reduced end on the shuttle driver shaft, preventing a shift of the driver gear from its concentric relation with the driver shaft. Loosening the clamp screws 502 enables the shuttle driver gear to be reclamped in any one of a number of different angular positions, corresponding to different timed relationships between the shuttle and the other stitch-forming devices. Change in the timed relationship of the shuttle produces no corresponding change in the times of actuation for the thread case retainer

members, inasmuch as the thread case retainer members are driven from the cam drum 500 which remains in fixed angular position on the driver shaft 464 at all times.

The variable speed looper mechanism is particularly well fitted for the purpose intended and is actuated by the vertical shaft 64 (Fig. 15), which is connected for rotation in a one to one driving ratio with relation to the sewing shaft 15. The vertical shaft 64 is also mounted in the machine frame in line with the axis of horn rotation. To drive the vertical shaft 64 and the main sewing shaft, the sewing shaft has secured to it a bevel gear 504 (see Fig. 2) meshing with a bevel gear 506 made fast to the upper end of an inclined shaft 508 extending through fixed bearings in the sewing head and in the base 46 of the horn. At the lower end of the inclined shaft 508 is a bevel gear 510 (see Fig. 15), meshing with a similar gear 512 having a hub extending through a bearing 514 in the subframe 46 and being keyed to a horizontal shaft 516, rotatable in bearings supported by the subframe. The shaft 516 also carries a bevel gear 518 engaging a bevel gear 520 at the lower end of the vertical shaft 64. The gear 506 on the inclined shaft 508 has two-thirds as many teeth as the gear 504 and the gear 510 has two-thirds as many teeth as the gear 512, so that the shaft 516 to which the gear 512 is keyed is rotated with the speed of the main sewing shaft. The gears 518 and 520 have the same number of teeth so that the vertical shaft 64 rotates with the main sewing shaft at a speed ratio of one to one.

The rotating variable speed ratio drive includes the vertical shaft 64 which passes through the cam drum 62 and a cage secured to its upper end (see Fig. 27). The cage includes a triangular plate integral with the shaft 64 and connected with a similar plate 522. The plate at the upper end of the shaft 64 and the plate 522 are connected by three vertical spindles 524 passing through the plates at their corners. One of the spindles 524 at the left of Fig. 27 has rotatable on it a gear segment 526 formed with teeth engaging those of a pinion 528 mounted in alignment with the vertical shaft 64. The pinion 528 is secured to the lower end of a driving shaft 530 for a set of step-up gears connected to the whirl 8 and arranged to drive the whirl two revolutions for one of the vertical shaft 64. As the cage comprising the plate 522 and the spindles 524 is rotated, the segment 526 is oscillated to impart a variable speed rotating drive to the step-up gear driving shaft 530. To oscillate the segment 526 it has passing through it approximately half way between its mounting spindle 524 and its toothed periphery a pin 532, the ends of which are secured in two eccentric straps 534 and 536. The strap 534 surrounds the eccentric 68, the hub of which is fixed by a key 538 to an intermediate partition within the spacer frame 42 (see Fig. 22). The plate 522 is rotatably mounted on the hub of an eccentric 540 passing through an opening at the upper end of a cylindrical enclosure 542 surrounding the variable speed drive and having a flange about its lower edge made fast by four screws 544 (Fig. 28) to a disk 546 (Fig. 27), in turn secured to the intermediate partition of the spacer frame 42. The key 538 also engages a keyway in the disk 546 to ensure assembly of the disk in proper angular relation to the other parts. The hub of the eccentric 540 is held from rotation in the cylindrical enclosure 542 by a key 548, the arrangement being such that the straps 534 and 536 rotate about their respective eccentricities together for imparting an oscillating movement to the gear segment 526. As the cage rotates about the respective hubs of the eccentrics, the vertical shaft 64 and the driving shaft 530 for the step-up gear set are held in alignment. The lower end of the shaft 530 is of reduced diameter to fit within a bearing in the triangular plate at the upper end of the vertical shaft 64, as illustrated in Fig. 27. The driving shaft 530 for the set of step-up gears has its mid-portion rotatable in the fixed hub of the eccentric 540.

and its upper end is rotatable in a bearing mounted within a projection 550 (Fig. 21) on the inner surface of the crown 38. Above the projection 550 the shaft 530 has fixed to it a driving gear 552 of the step-up set. The driving gear 552 meshes with a spur gear 554 keyed to the lower end of a hollow thread conducting shaft 556 rotatable in bearings 558 and 560 secured to the horn 10, the bearings 558 and 560 being mounted concentrically with the axis of horn rotation and with the needle 2. Between the bearings 558 and 560 the hollow shaft 556 is surrounded by a sleeve 562 keyed to the shaft with freedom of movement axially along the shaft. The sleeve 562 forms an overload slip joint with a bevel gear 564 rotatably mounted above it and provided with a V-notch cooperating with a projection on the sleeve 562, a compression spring 566 acting between the sleeve and a collar 568 on the hollow shaft to press the projection on the sleeve into the notch of the bevel gear 564 causing the bevel gear 564 to rotate with the hollow shaft. The upper end of the hollow shaft is provided with a nipple 570 through which the needle thread 145 is led to the whirl at the tip of the horn. The next gear of the step-up set is indicated at 574 and is of the bevel type meshing with the bevel gear 564. The bevel gear 574 is secured to the lower end of a countershaft 576 extending upwardly through the horn at an angle to the hollow shaft 556 and being connected in a conventional manner with the whirl 8, the over-all speed of rotation for the whirl being twice that of the sewing shaft 15.

To enable the machine to be turned over conveniently by hand the inclined shaft 508 has secured to it beneath the gear 506 a second gear 577 meshing with a bevel gear 578 secured to a horizontal shaft 579 (see Fig. 2). The shaft 579 passes through the left wall of the head frame 124 and at its left end outside the head frame a hand wheel 580 is secured to it. The shaft 579 is movable lengthwise to bring the gear 578 toward and from meshing engagement with the gear 577 so that the hand wheel does not need to be rotated while the machine is being operated under power. To lock the gear 578 out of engagement with the gear 577 a lever 581 is fulcrumed on the left side of the head frame below the shaft 579 and is yieldingly raised into engagement with it. When in engagement with the shaft 579 the lever 581 blocks the movement of the hand wheel 580 in a direction to move the gear 578 toward the gear 577. When it is desirable to turn the machine by hand the lever 581 is shifted away from the shaft 579 by grasping a handle portion of the lever, whereupon the hand wheel and gear 578 may be engaged with the gear 577. After turning the shaft manually to the desired position the hand wheel is drawn to the left and the lever 581 slips behind the hub of the gear 578 to lock it out of engagement with the gear 577.

To support the horn for rotation about an axis intersecting the needle and to enable its free rotation, the upper end of the crown 38 has surrounding a contracted portion at its upper end a friction reducing bearing 582 (see Fig. 21). The bearing 582 is surrounded, in turn, by and has clamped to its outer periphery the upper end of a cylindrical enclosure 583 formed with a downwardly extending skirt and a side opening about which is fitted a curved sliding door 584. The enclosure 583 may be rotated with the horn on its bearing 582 to bring its side opening into line with a similar opening 585 in the crown 38 so that convenient access is provided to the thread locks, their operating connections and other operating parts. The door 584 fits within parallel grooves in the enclosure 583 to enable the door to slide throughout a full 360° rotation on the enclosure, affording easy assembly and adjustment of the parts inside the crown without removing the door from the enclosure.

The horn 10 is clamped by bolts 586 (see Figs. 1 and 21) to the upper surface of the cylindrical enclosure 75

583 and is rotatable with the enclosure on the bearing 582. To prevent movement of the opening 11 in the upper end of the horn out of alignment with the needle, the enclosure 583 has projecting from its inner surface 5 near its lower edge a circular rail 588 engaged by a series of rolls, one of which is shown at 590 in Fig. 21. The rolls 590 are rotatably mounted upon vertical shoulder bolts 592 clamped to projecting lugs on the crown 38.

The spacer frame 42 and the crown 38 above it enable the machine to operate effectively upon boots and shoes having extremely high cut uppers or upon bags or suitcases of great length. While operating upon shoes with uppers of normal height the machine is equipped with a readily removable shelf 594 (see Fig. 1) secured to the head frame 124 and formed with an opening surrounding loosely the lower end of the horn 10. When high cut shoes or other long articles are to be operated upon, the shelf 594 is removed by loosening a few shelf clamping bolts, one of which is shown at 595.

As has been stated, the illustrated machine is provided with driving and stopping mechanisms, including improved means for coordinating the operation of high- and low-speed driving clutches and a braking action in said mechanisms. The driving and stopping mechanisms are assembled in a single complete unit separately from the machine and demountably attached to the machine through the use of readily removable fastenings. The driving and stopping mechanism unit ordinarily is enclosed within the hollow of the subframe and is provided with a driving member and a driven member arranged for convenient alignment and for driving engagement with the horizontal shaft 516 in the machine (Fig. 15).

For removing or replacing the driving and stopping mechanisms in the machine these mechanisms are mounted in a single separate frame 596, best shown in Figs. 3 and 15. Other views of the driving and stopping mechanisms include Figs. 4 and 16 to 20 inclusive. The frame 596 of the driving and stopping mechanism has projecting from its sides four rolls 598, two on each side resting on a pair of fixed rails 600 (Fig. 1), one at either side of the subframe 46. The rails are attached to the inner sides of the subframe side walls. When the rolls 598 rest on the rails 600 the driven member and a control treadle connection for the driving and stopping mechanisms are automatically held in alignment with their cooperating parts in the machine so that operative connections may be completed conveniently. When it is found necessary to make adjustments or replacements in the driving and stopping mechanisms, extensions are connected to the rails 600, along which extensions the driving and stopping mechanisms may be rolled to remove them from the enclosure on the subframe as illustrated in Fig. 3.

The rail extensions are in the form of supplemental rails 602 having step cut ends secured by bolts 604 to similarly cut ends on the rails 600. To support the supplemental rails 602 they are connected together by a strut 606 bolted to the rails and provided with a socket for a pipe standard 608 resting at its lower end upon the floor to which the machine is attached. By rolling the driving and stopping mechanisms along the supplemental rails into the position shown in Fig. 3, all sides of the mechanisms are cleared of obstruction for convenience in servicing. For applying power to the driving and stopping mechanisms an electric motor 610 provided with V-belt pulleys 612 is mounted inside a hollow base 614 to the upper surface of which the subframe 46 is secured.

The driving member of the driving and stopping mechanisms consists of a double V-belt pulley 616 (see Fig. 16) arranged to be engaged by a pair of belts 618 surrounding the motor pulleys 612. When the mechanisms are in operating position the driven member of the driving and stopping mechanisms consisting of a

shaft 620 having its free end splined fits within a correspondingly shaped opening inside the bevel gear 512 (Fig. 15). The gear 512 forms one of the driving connections between the main sewing head and the mechanisms in the horn mounting structure. For securing the driving and stopping mechanisms from accidental displacement, the frame 596 has surrounding the driven shaft 620 a perforated flange and at its mid-portion a perforated lug 621 through the perforations of which pass a number of clamp bolts 622 into engagement with threaded openings 624 in the subframe 46.

For coupling the driving and driven members of the driving and stopping mechanisms the high- and low-speed clutches are arranged to be controlled selectively by a treadle. For controlling the clutches a system of interlocking connections is also provided to prevent disengagement of the low-speed clutch whenever the driven shaft is rotating at a speed higher than that of the low-speed clutch, so as to subject the driven shaft to a braking force rather than to be rotated by the low-speed clutch. For this purpose the interlocking connections include a lockout member controlled by the braking force applied to the driven member of the driving and stopping mechanisms for holding the low-speed clutch momentarily in engagement until the speed of the driven member is reduced to that of the low-speed clutch.

The speed of the high-speed clutch is that required for the maximum rate of sewing operations intended to be performed by the machine. The low-speed clutch operates at a sufficiently reduced rate of rotation to avoid the necessity of utilizing a separate frictional brake, the rotating parts of the machine providing sufficient friction to enable them to drift to an approximate stopping position after the low-speed clutch has been disengaged. To ensure positive stopping at the exact position in which the machine is intended to come to rest, a yielding stop is provided acting in a predetermined position of a rotating part carried by the driven member of the driving and stopping mechanism. Also, the interlocking connections cause the machine to be started by the low-speed clutch and then the driving torque to be transferred to the high-speed clutch according to the degree to which the control treadle is depressed. Thus, the driving and stopping mechanism fundamentally is relatively simple with all of its heavier power transmitting parts reduced to a minimum number. In this way the space occupied by the driving and stopping mechanisms is less than with previous mechanisms for transmitting and controlling corresponding amounts of power, all of the interlocking connections being smaller and lighter in weight than the power transmitting parts. Even though the interlocking connections are somewhat more complex than those employed with prior driving and stopping mechanisms their lightness renders them capable of rapid movement with great durability for the reason that they are not subject to heavy forces.

The high-speed driving clutch consists of a flanged disk portion of the driving pulley 616. The pulley 616 is rotatably mounted on friction reducing bearings 625 retained on the rearward end of the driven shaft 620 by a nut 628 engaging a reduced threaded portion of the driven shaft. The extreme end of the driven shaft 620 is reduced still more and rotates in a bearing 630 secured in a plate 632 clamped by screws, one of which is shown at 634, to a rearward projection of the frame 596 for the driving and stopping mechanisms.

The driven member of the high-speed clutch includes a cone shaped peripheral facing 636 engageable with a similar shaped inner surface of a flange on the driving pulley 616 (see Fig. 15). The facing 636 is supported by a wheel 638 clamped to a sleeve 640 surrounding the driven shaft 620. The sleeve 640 is keyed to the shaft and is capable of shifting movement along the shaft toward and from the driving pulley 616. For shifting the driven member of the high-speed clutch toward and

from the driving pulley 616, the sleeve 640 also has secured to it, in contact with the wheel 638, a peripherally grooved collar 642, the groove of which is engaged by wear blocks 644 (see Fig. 16) pivoted to the lower ends of a yoke 646 through the spaced portions of which passes a fulcrum bar 648 secured between its ends in the driving frame 596 in a position above and at right angles to the driven shaft 620. The intermediate portion of the yoke has a rectangular opening through which passes an operating arm 650 loosely surrounding the fulcrum rod 648 and engageable at either of its sides with one of a pair of screws 652 threaded through upstanding lugs on the yoke at either side of its intermediate opening and provided with check nuts 654 to lock the screws in the lugs.

The low speed clutch surrounds the sleeve 640 (Fig. 16) and includes a driving member in the form of a worm wheel 656 rotating on a cylindrical portion of a flanged drum 658 (see Fig. 15) mounted concentrically with the driven shaft 620 and fixed by screws 660 to the driving frame 596. The screws 660 pass through the flanged portion of the drum 658 into threaded engagement with a portion of the frame 596. Between the drum 658 and the worm wheel 656 is disposed a thrust ball bearing 662 acting to take up the pressure of a low-speed driven clutch member as it engages a conical surface within the worm wheel 656.

The low-speed driven clutch member includes a facing 664 on a wheel 666 rotatably mounted on bearings 668 clamped to the sleeve 640. The wheel 666 has three parallel spring pressed plungers 669 arranged to engage the worm wheel 656 to prevent vibratory effects in the clutch. The arrangement is such that when the sleeve 640 is shifted forwardly by the yoke 646, the low-speed clutch 656, 664 is engaged and when shifted rearwardly the high-speed clutch 636, 616 is engaged and the low-speed clutch is disengaged. The sleeve 640 together with its high- and low-speed clutch driven wheels thus comprises a combined high- and low-speed clutch driven member for both clutches.

To drive the worm wheel 656 of the low-speed clutch, the wheel is engaged by a worm 670 (see Fig. 16) secured to one end of a shaft 672 rotatable in the driving frame 596. The other end of the shaft 672 carries a helical gear 674, the teeth of which mesh with those of a similar gear 676 secured to the forward end of a countershaft 678 also rotatable in the frame 596. The rearward end of the countershaft 678 has secured to it a V-belt pulley 680 connected for rotation through a belt 682 with a belt receiving groove 684 on the main driving pulley 616. The driving frame 596 is so constructed that all of the power transmitting parts, including the worm 670 and their supporting shafts operate in an oil bath contained within the frame. To prevent the escape of oil from the outer end of the worm shaft 672, the worm is enclosed beyond the end of its shaft by a disk 686 (Fig. 15) secured to the frame by screws 688. In starting the machine in operation the sleeve 640 is first shifted forwardly to engage the low-speed clutch and then shifted rearwardly to engage the high-speed clutch.

To shift the combined high- and low-speed clutch member including the sleeve 640 first forwardly and then rearwardly through connections with the treadle, the yoke actuating arm 650 has passing through its upper end a pin 690 forming a pivotal connection with one end of a toggle comprising a pair of links 692 and 694. The links 692 are of H-shape, spaced portions of the link 694 embracing those of the link 692 at their central joint. The central joint between the links comprises a pin 696 passing through the two links and the end of the link 694 opposite the pin 696 is connected by a pin 698 with a square head on a rod 700. The square head on the rod 700 has a reduced cylindrical portion slidably mounted in a passage formed in a lug 702 of the driving frame 596. The rod 700 extends through an opening in an end

wall of the passage in the lug 702 to confine a compression spring 703 between the head of the rod and the end wall of the passage. Beyond the lug the rod has a pair of check nuts 704 threaded thereon to prevent displacement of the rod. The check nuts 704 engage the end of the lug and determine the position of the toggle links 692 and 694 when the machine is at rest, as illustrated in the drawings. In the position of the toggle links shown, with the central joint pin 696 below the end pins 690 and 698, the yoke 646 holds the driven clutch member sleeve at an intermediate position with both the high- and low-speed clutches disengaged. In starting the machine in operation the toggle links 692 and 694 are moved from positions of misalignment, shown in the drawings, to positions where the pins 696, 690 and 698 are in alignment. As the toggle links approach positions of pin alignment the yoke 646 is rocked about its fulcrum bar to engage the low-speed clutch. The central joint pin 696 is then raised further to bring the link pins again into positions of misalignment and to rock the yoke 646 until the low-speed clutch is disengaged and the high-speed clutch is engaged.

The connections for raising the central joint of the toggle links 692 and 694 include a link 706 through a mid-portion of which passes the pin 696 and through the upper end of which passes a pin 708 forming a connection with a lever 710 secured to a rockshaft 712 rotatably mounted in upwardly projecting arms on the driving frame 596. The lever 710 has a short arm overlying a lateral projection on one arm of a three-armed lever 714 rotatably mounted on the shaft 712. A second arm of the lever 714 is pivotally connected to the upper end of an irregularly bent link 716 (Fig. 15), the lower end of which is pivotally connected to an arm of a horizontal lever 718 fulcrumed on a stud 720 passing through a slotted lug at the bottom of the driving frame 596. Another arm of the lever 718 projects forwardly and has a pivot 722 connected to a yielding link 724 (see Fig. 1) which extends between the lever 718 and a treadle 726. The treadle is rotatably mounted on a stud 728 fixed in a base 614 of the machine. To maintain the treadle yieldingly in raised position a tension spring 730 is stretched between it and the machine base 614, the treadle projecting through a slot 732 in the front wall of the base into a position accessible to the operator. The connections described afford a convenient treadle control for the high- and low-speed clutch. When the treadle is depressed the yielding link 724 prevents the transmission of impulses from the driving and stopping mechanism to the treadle, thus avoiding discomfort for the operator. When the driving and stopping mechanisms are to be removed for servicing, it is necessary to release the driving frame from the bolts 622 and to remove the control linkage pivot 722. The driving frame is then free to be withdrawn from the subframe 46. To limit the movement of the treadle by the spring 730 while the driving and stopping mechanisms are removed, the upper surface of the treadle within the base is engaged by a stop bracket 734 secured within the base. To prevent the application of excessive pressure through the toggle links and yoke 644 to the low-speed clutch the check nuts 704 on the rod 700 are adjusted to cause compression of the spring 703 just as the toggle links come into alignment, the force of the spring 703 then being transmitted through the treadle connections to the low-speed clutch. When the high-speed clutch is engaged the force applied thereto acts directly to press the check nut 704 against the end wall of the frame lug 702. In this way the regulation of machine speed is effected directly in proportion to the depression of the treadle acting through the connections.

To shift the central joint pin 696 between the toggle links away from its high-speed clutch operating position and to ensure that the combined high- and low-speed driven clutch member will be returned to an intermed-

iate position without being driven by either clutch, the rockshaft 712 has secured to its right end a downwardly extending arm 735 having a forked portion embracing a sliding rod 736. The rod 736 is surrounded at its rearward end by a hollow bolt 738 and at its forward end it projects through a threaded sleeve 740. The bolt 738 engages a threaded opening in the rear wall of the driving frame 596 and the sleeve 740 engages a threaded opening in a lug of the frame 596. Between its ends the rod 736 is surrounded by a toggle return spring 742 compressed between the bolt 738 and a collar 744 pinned to the rod 736. The action of the spring 742 compresses the collar against the lower end of the arm 735, rocking the shaft 712 in a direction to lower the central joint pin 696 and moving the combined driven clutch member to an intermediate position. The position of the sleeve 740 limits the expansion of the spring 742 and thus determines the intermediate position of the combined driven clutch member. To adjust the intermediate position of the combined driven clutch member, the threaded sleeve 740 is formed with a hexagon head through which it may be rotated to change its lengthwise position.

The yielding stop for determining the exact position in which the machine comes to rest is moved automatically into active position through connections controlled by the speed of rotation of the driven shaft 620 in the driving and stopping mechanisms and is moved away from active position by connections actuated by the control treadle 726 when the machine is started in operation. The yielding stop is arranged to engage a driven member of the driving and stopping mechanisms and for this purpose the driven stop member is mounted on a disk 746 rotated through an adjustable connection with the driven shaft 620. The driven stop member comprises a buffer lever 748 (see Fig. 16) fulcrumed on a screw 750 threaded into the disk 746. The yielding stop consists of a roll 752 movable toward and from the path described by one end of a buffer lever 748 as it rotates with the disk 746. The roll 752 is rotatably mounted on an L-shaped arm of a gear segment 754 through the hub of which projects a stud 756 rotatably mounted at its ends in a recessed section of a lower arm on a lever 758 fulcrumed for free rotation on a shaft 760. The shaft 760, as best shown in Figs. 15, 16, 18, 19, and 20 is fixed in spaced lugs of the driving frame 596 between which the lever 758 is located. When the machine is at rest the roll 752 is held in engagement with the buffer lever 748 by a detent 761 pivoted on a pin 762 mounted in the driving frame 596 (see Figs. 15 and 16). The detent 761 is urged yieldingly into engagement with the upper arm of the stop lever 758 by a spring 764 connected at one end to a pin carried by the detent and at its other end to the driving frame 596.

To absorb excessive shocks when the buffer lever 748 (Fig. 16) engages the stop roll 752 an offset portion of the lever 748 is acted upon by a coil spring 766 surrounding a projection on the lever 748. To retain the spring 766 in compressed position, a screw 768 enters the spring at one end and is threaded through a lug on the disk 746 against which the spring is compressed. To limit the expansion of the spring 766 an arm of the buffer lever 748 engages an edge surface on the lug through which the screw 768 passes. The adjustable connection between the disk 746 and the shaft 620 includes a pair of screws 770 passing through slots in the disk 746 and into threaded engagement with bosses on a cam plate 772 secured to the forward end of the shaft 620. By loosening the screws 770, the disk 746 may be given a limited angular rotation on the shaft 620 to cause the buffer lever 748 to engage the stop roll 752 when the driven shaft 620 is in one of a number of different angular positions.

To cause the presser foot to clamp a new shoe on the shoe supporting horn the detent 761 is disengaged from the upper arm of the yielding stop lever 758 by the first

short depressing movement of the treadle when the machine is at rest. For this purpose the detent has extending beneath it an arm of a releasing lever 774 rotatably mounted on a shaft 776 fixed in the upper portion of the driving frame 596 beneath the lug 702 (Fig. 15). A rearwardly extending arm of the lever 774 has a roll 778 arranged to be engaged by a cam segment 780 projecting from the three-arm lever 714. Disengagement of the detent from the lever 758 permits limited rocking movement of the stop lever 758 about the shaft 760 out of the path of the buffer lever, the roll 752 entering a cut away section along the periphery of the disk 746.

Rocking movement of the stop lever 758 out of the path of the buffer lever is imparted to it through connections running from the presser foot lifting link 345 (Fig. 1) which is forked at its lower end and embraces the right end of an arm 782 (see also Figs. 18 to 20, inclusive), rotatable about the rearward end of the shaft 760. The hub of the arm 782 has projecting from it a pair of tongues embracing an angular plate 784 (Figs. 19 and 20), clamped by a screw 786 to an arm 788 having an elongated hub mounted for rotation and lengthwise sliding movement on a sleeve 790 through which the shaft 760 passes. The hub of the arm 788 has projecting forwardly from it in parallel relation thereto a rack bar 792 (Figs. 16 and 19). The rack bar 792 fits within the recessed section of the lower arm on the stop lever 758 and engages with its teeth the gear segment 754. The arrangement of the rack bar within the recessed section of the lever 758 causes the stop lever 758 to rotate on the shaft 760 together with the rotation of the arm 788 and its hub on the sleeve 790 while leaving the hub of the arm 788 free to slide lengthwise of the sleeve 790. To press the roll 752 yieldingly into the path of the buffer lever 748 the angular plate 784 engages one end of a compression spring 793 supported at its opposite end in a bore formed in the shaft 760. The connection afforded by the tongues on the hub of the arm 782 surrounding the plate 784 causes the arm 782 to rotate on the shaft 760 also with the arm 788. Thus, the lever 758 and the arm 782 rotate together on the shaft 760, the force of the presser foot spring being impressed on the stop lever 758 and being restrained when the detent 761 latches the stop lever.

For actuating the stop lever 758 to lift the presser foot from engagement with the work, the periphery of the disk 746 acts as a cam on the stop roll 752, the disk being formed with a gradually increasing diameter (Fig. 16). As the driven shaft 620 performs its final rotation at the end of a sewing operation, the stop roll 752 is moved away from the shaft 620 by the periphery of the disk 746 and the stop lever 758 is latched by the detent 761 in presser foot lifting position.

To cause the stop roll 752 to be moved out of the path of the disk 746 before sewing operations are started, the segment 754 is rotated on the stud 756 to swing the stop roll 752 rearwardly of the disk 746. Rearward swinging movement is imparted to the roll 752 through the engagement of the gear segment 754 with the rack bar 792 as the control treadle 726 is depressed beyond the position where the lever 758 is released from the detent 761. A downwardly extending arm on the detent releasing lever 774 (see Fig. 19) carries a roll 794 engaging a groove 796 at the forward end of the hub of the arm 788, acting to press the hub of the arm 788 and the rack bar 792 forwardly along the sleeve 790. Forward movement of the rack bar 792 causes the segment 754 to swing from the solid line position of Fig. 19 to the broken line position where the roll 752 is held clear of the buffer lever 748 and the disk 746.

The lockout in this feature of the invention is best shown in Fig. 18 of the drawings. The lockout prevents re-engagement of the stop roll 752 with the buffer lever 748 until the braking force applied to the driven member

of the low-speed clutch is terminated in the driving and stopping mechanisms. The lockout consists of a hook 798 mounted for engagement with a roll 800 at the lower end of the link 706. When the hook 798 engages the roll 800 the low-speed clutch is locked in engagement, the toggle links 692, 694 being held in alignment by the hook. The hook 798 is riveted to the central portion of a yoke 802 having oppositely projecting pivots 804 rotatably mounted in bearings in the driving frame 596. The hook 798 is held yieldingly out of engagement with the roll 800 by a spring 806 stretched between it and the driving frame.

To bring the hook 798 into locking engagement with the roll 800 the lower separated ends of the yoke carry 15 a pair of rolls 808 engaging a radially projecting flange on a collar 810. The collar 810 loosely surrounds a drum 812 secured to the driven sleeve 640. Extending from the drum 812 along the sleeve 640 is a projection 814 which enters a cutout space near the rim of the low speed wheel 666. The cutout space in the wheel forms shoulders 816 and 818 in the rim of the wheel between which the projection 814 oscillates depending upon the torque applied to the wheel by the low-speed driving 20 worm wheel 656. While the low-speed clutch is driving the machine the projection 814 assumes a position in engagement with the shoulder 818 on the rim of the wheel 666. When the wheel 666 of the low-speed clutch member is disengaged from the driving wheel 656, the projection 814 remains in contact with the shoulder 818 by 25 reason of a spring 820 stretched between a pin 822 on the end of the projection 814, and a similar pin 824 on the wheel 666. Movement of the projection between the shoulders on the wheel 666 produces relative movement between the drum 812 and the collar 810, the collar having a series of pins 826 projecting from it into openings 828 in the rim of the wheel 666. Relative movement between the drum 812 and the collar 810 causes the collar to move along the shaft by reason of a set of radial studs 830 carried by the collar 810 engaging helical slots 832 in the drum 812. Relative movement between the collar 810 and the drum 812 takes place only when a braking force is applied to the driven shaft through the low-speed clutch, the projection 814 moving away from the shoulder 818 and against the shoulder 816 of the driven low-speed clutch wheel 666. Such relative movement causes the flange of the collar 810 to press the rolls 808 rearwardly and to engage the lockout hook 798 with the roll 800. As soon as the application of braking force to the low-speed driven clutch wheel 666 is terminated, the spring 820 returns the collar 810 and the drum 812 to their original relationship.

In addition to the lockout hook 798 for preventing re-engagement of the stop roll 752 with the lever 748 while braking force is being applied to the low-speed clutch, the illustrated driving and stopping mechanisms are provided with a lockout latch 834 (Fig. 18) engaging a shoulder on the link 694 (see Figs. 15 and 16) to hold the pin 696 forming the central joint of the toggle links 692, 694 from downward movement past the position in which the low-speed clutch is engaged and then disengaged. These connections include a laterally projecting arm of the hook 798 provided with a button 836 which engages the plate 784 whenever a braking force is being imparted by the low-speed clutch. Pressure on the plate 784 moves the arm 788 to which it is attached forwardly along the sleeve 790 or holds it in forward position, so that the rack bar 792 will operate to hold the stop roll 752 out of the path of the buffer lever 748.

The lockout latch 834 is secured to the right end of a shaft 838 rotatably mounted in the driving frame 596 and is provided at its right end with a dog 840 secured thereto. The latch 834 is held yieldingly in latching position with relation to the link 694 by a spring 842 stretched between the latch and a fixed portion of the frame. The latch 834 is normally held away from the

link 694 against the force of the spring 842 by engagement with the dog 840 of a projection from the hub of an arm 844. The lower end of the arm 844 has a roll 846 rotatable on it, engaging a groove 848 at the end of the arm 788. The groove 848 forms an angle of less than 90° with the axis of the sleeve 790 on which the arm is mounted, so that when the arm 788 is raised and the detent 761 is acting on the stop lever 758 to hold the stop roll 752 in the path of the buffer lever 748, the projection on the arm 844 holds the latch 834 away from the link 694, the machine being at that time either in stopped position or nearly so. The toggle links 692, 694 at that time are in their lowermost misaligned position. As soon as the treadle 726 is depressed to start the machine in operation, the detent 761 releases both the stop lever 758 and the arm 788 for counterclockwise rotation, as viewed in Figs. 16 and 18, the angular relation of the groove 848 swinging the arm 844 forward to permit the latch 834 to engage the link 694. As the machine is started and later slowed down, movement of the hub of arm 788 swings the arm 844 in a direction to disengage the latch 834 from the link 694. If, however, braking action is required of the low-speed clutch to slow the machine, the hub of arm 788 is caused to slide forwardly on the sleeve 790 and the arm 844 swings again in a direction to re-engage the latch 834 with the link 694. Thus, the lockout acts on two separate sets of connections to accomplish a similar result but at different times.

After the braking action of the low-speed clutch is terminated and the driven shaft 620 of the driving and stopping mechanisms has nearly reached its final stopping position, the buffer lever 748 is about to be engaged by the positive stop roll 752. The low-speed driving clutch is disengaged at this time and the machine coasts to its stopping position until the buffer lever 748 contacts the stop roll 752. While these actions are taking place the presser foot is being lifted and the timing of the thread lock movements is being changed. These operations both are performed by connections to the arm 782. The arm 782 carries a ball-headed pin 849 engaged by a socket at the upper end of a link 850. The lower end of the link 850 has a similar socket engaging a pin 851 secured in a rearwardly projecting arm of a lever 852 fulcrumed on a pivot 853 rigidly mounted in the driving frame 596. A forwardly projecting arm of the lever 852 engages the rearward end of the push rod 214 for causing the thread lock timing change.

To assist in the free operation of the presser foot lifting and thread lock timing change connections, the downwardly extending presser foot lifting link 345 (Fig. 18) carries a collar 854 from which projects a pin engaged by the lower end of a spring 856, the upper end of which is connected to a fixed part within the head frame 124. The spring 856 assists in rocking the hub of the arm 788 in a direction to maintain the stop roll 752 in contact with the cam disk 746 during the final rotation of the driven shaft 620.

Before the positive stop roll 752 is permitted to engage the buffer lever 748 it is necessary to ensure that the low-speed driving clutch is disengaged and a coasting period of adequate length takes place so that the momentum of the moving parts in the machine may be absorbed without breakage. For this purpose the stopping mechanism is provided with a timing pawl which prevents disengagement of the low-speed clutch.

The timing pawl is actuated by the cam plate 772 which is engaged by a roll 858 carried by the lower arm of a V-shaped lever 860 pivoted on a stud 862 secured in the driving and stopping frame 596 and the upper arm of the lever is pivotally connected to the lower end of a link 864, the upper end of which is similarly connected to an arm of the timing pawl in the form of a lever, indicated at 866. The timing pawl lever is rotatable on a fixed screw stud 868, the pawl arm of which lever is uppermost and is movable toward and from the forward

end of the sliding rod 736. Connected to the pawl arm of the lever 866 is a spring 870 acting through the connections described to hold the roll 858 in contact with the periphery of the cam plate 772.

The cam plate 772 is shaped throughout the major portion of its periphery with a uniform radius, such that the timing pawl is held in yielding engagement with the rod 736. As the machine is coming to rest during its low-speed rotation the rod 736 moves forwardly while the low-speed clutch comes into driving engagement and a shoulder 872 at the end of the rod is projected against the timing pawl arm of the lever 866, stopping the forward movement of the rod 736. In the position at which the forward movement of the rod 736 is stopped by the timing pawl, the low-speed driving clutch is held in engagement until the timing pawl moves away from the rod 736. Movement of the timing pawl away from the rod 736 occurs at a point in the rotation of the driven shaft 620 approximately 180° of rotation from the position of the shaft in which the buffer lever 748 engages the stop roll 752. For disengaging the timing pawl from the rod 736 the periphery of the cam plate 772 has an enlargement 874 of sufficient radius to lift the pawl away from the shoulder 872. However, approximately 20° from the position of the driven shaft 620 in which the buffer lever 748 engages the stop roll 752, the latch 834 releases the toggle link 694 and the machine then comes to rest with the buffer lever in engagement with the stop roll 752.

During the final rotational movements of the main sewing shaft 15 (see Fig. 10) as the machine is coming to rest, a one-shot lubricating system is actuated to apply oil to many of the operating parts. The lubricating system is caused to be actuated by a connection with the presser foot lifting rockshaft 238 which carries at its rearward end the bell crank 344. For this purpose the upper arm of the bell crank 344 is pivotally connected to a rod 876 having a threaded end passing through a perforated block 878. The block 878 has a pair of trunnions entering openings in a forked arm of a lever 880 mounted for rotation on a stud 882 fixed in a bracket 884 secured to the sewing frame 124. Another arm of the lever 880 is also forked and has open-ended slots entering its forked portions, within the slots of which are positioned a pair of aligned pins, one of which is shown at 886 projecting from the upper end of a vertical plunger 888. The plunger 888 is slideable in a cylinder 890 of an oil pump (see also Fig. 29) and at its upper end the plunger has a pair of spaced flanges between which is rotatably mounted a roll 892. The roll 892 engages a cam disk 894 secured to the rearward end of the sewing shaft 15.

As the stopping mechanism is being actuated and the presser foot is being lifted at the end of a seam the bell crank 344 is rotated in a clockwise direction, as viewed in Fig. 29, pulling the rod 876 through the block 878 and pressing the roll yielding against the cam disk 894. For these purposes the rod is surrounded by a coil spring 896 compressed between the block 878 and a pair of check nuts 898 on the threaded portion of the rod. Just before reaching its final stopping position the spring 896 raises the plunger and a projection 900 on the cam disk 894 engages the roll 892 to depress it sufficiently to eject a quantity of oil.

The lubrication cylinder 890 is connected with an inlet tube 902 and an outlet tube 904, the flow through which is controlled by ball valves 906 and 908. The inlet tube 902 dips into a sump 910 in the head frame 124 beneath the sewing shaft 15 and the outlet tube 904 runs through branch connections indicated at 914 (Fig. 10) with a 10 to the moving parts of the machine. One of the branch connections is indicated at 914 (Fig. 10) with a nozzle disposed above the cam 226 for lubricating the rolls 228 and 230 engaging the cam. When the machine is stopped, the plunger 888 is given a single reciprocation, ejecting a shot of oil. Upon restarting the machine the roll 892 is given a second oil ejecting reciprocation. As

the presser foot is being lowered into engagement with a new shoe, the rod 876 moves toward the left (Fig. 10), releasing the compression of the spring 896 and permitting the plunger 888 to be depressed without causing it to be raised again. Depressing the plunger 888 ejects the second shot of oil onto the moving parts of the machine. The plunger 888 then remains stationary in depressed position until the machine stops.

Referring to the time chart in Fig. 31, it will be apparent from the curve designated "Thread Locks" that the solid line represents the action of the front and rear thread locks 30, 32. At the stopped or 0° position of the sewing shaft the front lock 30 is normally closed and the rear lock 32 is open. The timing of the thread locks is changed by the driving and stopping mechanisms as the machine is coming to rest through the connections including the lever 852 (Fig. 18), the push rod 214, the arm 212 and the cam lever 174 (best shown in Fig. 24). The change of timing causes the front lock 30 to open and the rear lock 32 to close, as illustrated in the broken line 918 forming a part of the "Threaded Locks" curve. At the same time that the presser foot is lifted from engagement with the work, the lubricating system applies oil to the parts.

The stitch-forming and work-feeding devices of the machine operate in accordance with the movements indicated by the curves identified as "Awl," "Needle," "Needle Feeding Movement," "Presser Foot Lift," "Presser Foot Lock," "Loop Spreader," and "Shuttle." The relationship of work resting on the top of the horn 10 to the needle and awl is indicated by the cross-hatched space between the two horizontal dot-dash lines identified by the legend "1 1/4" Work."

The work is fed by lateral movements of the needle 2 in timed relation to the reciprocating movements of the needle and awl in accordance with the curve designated, "Needle Feeding Movement," the presser foot being lifted from engagement with the work before the feeding movement starts, as indicated in the "Presser Foot Lift" curve. After the presser foot has lifted from engagement with the work it re-engages the work yieldingly and is locked in work clamping position at a time indicated by the "Presser Foot Lock" curve. After retracting from the work, the loop of thread carried by the needle is opened for entry of the shuttle in a manner illustrated in the curve designated "Loop Spreader," the shuttle entering the spread loop at about 210° in each sewing cycle, as illustrated in the solid part of the "Shuttle" curve. The particular shuttle beak which carries the loop of thread passes the loop about the shuttle and thereafter releases it in a timed relation to the other stitch forming devices, as indicated by the dotted portion of the "Shuttle" curve.

The operation of the combined thread controller and pull-off is illustrated by the curve identified as "Thread Pull-off Cam" and "Controller Cam." These two cams are the ones formed by the grooves 60 and 94 (best shown in Fig. 23). The two cams together actuate the arcuate guide bar 72. Each end of the guide bar 72 is moved by one of the cams so that the respective curves together illustrate the movements imparted to both ends of the guide bar. When the slider 80 of the guide bar is moved to either end, the corresponding movements of the combined controller and pull-off will correspond to the movements illustrated by the particular curve. In actual operation of the machine, however, the slider ordinarily is usually adjusted to a position somewhere between the ends of the guide bar so that a movement of the combined controller and pull-off is that indicated by a line part way between these two curves, as for instance, the broken line 920. In other respects, the timing of the stitch forming devices in the machine is similar to that disclosed in inventors' prior Patent No. 2,670,701.

Certain features of the invention herein disclosed form the subject matter of divisional applications as follows:

Serial No. 673,809, filed January 24, 1957, relating to driving and stopping mechanisms; Serial No. 738,810, filed May 20, 1958, relating to feeding and stitch-forming mechanisms; and Serial No. 750,510, filed July 23, 1958, relating to presser foot mechanism.

The invention having been described what is claimed is:

1. A sewing machine having stitch forming devices including a hook needle, a looper and a stitch-setting loop taker, in combination with means including thread measuring and controlling devices comprising spaced-apart means for immovably gripping two portions of the needle thread including a front thread lock and a rear thread lock mounted along the path of the thread in the machine at the opposite side of the work from the needle and loop taker, and means including a single thread controller and pull-off acting on the thread between the thread locks to pay out through the front lock thread equal in amount only to that required by the threaded needle during its withdrawal through the work, the paying out action of the controller and pull-off taking place at a time when the thread is immovably gripped by the rear lock.

2. A sewing machine having stitch-forming devices including a hook needle, a looper and a stitch-setting loop taker, in combination with means including thread measuring and controlling devices comprising a pair of thread locks mounted along the path of the thread in the machine at the opposite side of the work from the needle and loop taker, and means including a single combined thread controller and pull-off acting on the thread between the thread locks to pay out thread equal in amount only to that required by the threaded needle during its withdrawal through the work, and to draw back thread after engagement of each needle loop with the loop taker in an amount less than that required for the threaded needle during withdrawal through the work.

3. A sewing machine having stitch-forming devices including a hook needle, a looper and a stitch-setting loop taker, in combination with means including thread measuring and controlling devices comprising a pair of thread locks mounted along the path of the thread in the machine at the opposite side of the work from the needle and loop taker, and means including a single combined thread controller and pull-off acting on the thread between the thread locks to pay out thread equal in amount only to that required by the threaded needle during its withdrawal through the work, and to draw back thread after engagement with the loop taker in an amount less by the length of thread measured than that required for the threaded needle during withdrawal through the work.

4. A sewing machine having stitch-forming devices including a hook needle, a looper and a stitch-setting loop taker, in combination with thread measuring and controlling devices comprising a pair of thread locks mounted along the path of the thread in the machine at the opposite side of the work from the needle and loop taker, a single combined thread controller and pull-off acting on the thread between the thread locks to pay out thread during the withdrawal of the threaded needle through the work, and means including two separate mechanisms for actuating the combined thread controller and pull-off, one of which causes the thread to be payed out in an amount sufficient only for the threaded needle to be withdrawn through the work without sliding movement of the thread in the needle hook and the other of which provides a length of thread sufficient for the formation of each stitch.

5. A sewing machine having stitch forming devices including a hook needle, a looper and a stitch setting loop taker, in combination with thread measuring and controlling devices comprising a pair of thread locks mounted along the path of the thread in the machine at the opposite side of the work from the needle and loop taker, a single combined thread controller and pull-off acting on

the thread between the thread locks to pay out thread during the withdrawal of the threaded needle through the work, means including two separate mechanisms for actuating the combined thread controller and pull-off, one of which causes the thread to be payed out in an amount sufficient only for the threaded needle to be withdrawn through the work without sliding movement of the thread in the needle hook and the other of which provides a length of thread sufficient for the formation of each stitch, and means including a proportioning connection between the two mechanisms adjustable in accordance with the thickness of the work operated upon.

6. A sewing machine having stitch-forming and stitch-setting devices including a hook needle, a looper, a loop taker and a thread measuring pull-off, in combination with means including a pair of thread locks, one mounted along the path of the thread in the machine in front of the pull-off and one mounted along the path of the thread at the rear of the pull-off comprising fixed anvil blocks, clamp shoes acting on the thread engaged with the anvil blocks, means including independent carrier arms for the clamp shoes, and a common stud on which the carrier arms are rotatably mounted for separate movement in opposite directions to actuate the clamp shoes toward the anvil blocks.

7. A sewing machine having stitch-forming and stitch-setting devices including a hook needle, a looper, a loop taker and a thread measuring pull-off, in combination with means including a pair of thread locks, one mounted along the path of the thread in the machine in front of the pull-off and one mounted along the path of the thread at the rear of the pull-off comprising fixed anvil blocks, clamp shoes acting on the thread engaged with the anvil blocks, independent carrier arms for the clamp shoes, a common stud on which the carrier arms are rotatably mounted and spring means for pressing the carrier arms in opposite directions for separate movement of the clamp shoes toward and from the anvil blocks, and a separate operating arm also rotatably mounted on said stud for movement toward and from the carrier arms to open and close the locks alternately.

8. A sewing machine having stitch-forming and stitch-setting devices including a hook needle, a looper, a loop taker and a thread measuring pull-off, in combination with means including a pair of thread locks, one mounted along the path of the thread in the machine in front of the pull-off and one mounted along the path of the thread at the rear of the pull-off, said locks comprising fixed anvil blocks, clamp shoes acting on the thread engaged with the anvil blocks, independent carrier arms for the clamp shoes, a common stud on which the carrier arms are rotatably mounted for separate movement of the clamp shoes toward and from the anvil blocks, an operating block between the carrier arms, separate springs disposed between the carrier arms and the operating block, and means for increasing the pressure of one of said springs on one carrier arm or the other as the operating block is moved in opposite directions relatively to the arms.

9. A sewing machine having stitch-forming and stitch-setting devices including a hook needle, a looper, a loop taker and a thread measuring pull-off, in combination with means including a pair of thread locks, one mounted along the path of the thread in the machine in front of the pull-off and one mounted along the path of the thread at the rear of the pull-off, said locks comprising fixed anvil blocks, clamp shoes acting on the thread engaged with the anvil blocks, independent carrier arms for the clamp shoes, a common stud on which the carrier arms are mounted for separate movement of the clamp shoes toward and from the anvil blocks, separate springs disposed between the carrier arms, an operating block to increase the pressure of one of said springs on one carrier arm or the other as the operating block is moved in opposite directions relatively to the arms, and projections on the arms and projection engaging fingers on the block

for limiting relative movement between the block and arms to open the locks against the pressure of the springs alternately as the operating block is moved in opposite directions.

- 5 10. A sewing machine having stitch-forming and stitch-setting devices including a hook needle, a looper, a loop taker and a thread measuring pull-off, in combination with means including a pair of thread locks, one mounted along the path of the thread in the machine in front of the pull-off and one mounted along the path of the thread at the rear of the pull-off, said locks comprising fixed anvil blocks, clamp shoes acting on the thread engaged with the anvil blocks, independent carrier arms for the clamp shoes rotatably mounted on a common stud for separate movement of the clamp shoes toward and from the anvil blocks, separate springs disposed between the carrier arms, an operating block to increase the pressure of one of said springs on one carrier arm or the other as the operating block is moved in opposite directions relatively to the arms, and projections on the arms and projection engaging fingers on the block for limiting relative movement between the block and arms to open the locks against the pressure of the springs alternately as the operating block is moved in opposite directions, there being 15 two fingers on the operating block between which are disposed the projections on the carrier arms, arranged to increase the force of a spring acting on one carrier arm before a finger on the operating block engages a projection on the other carrier arm.
- 20 25 30 35 40 45 50 55 60 65 70 75 80 85 90 95
11. A sewing machine having stitch-forming and stitch-setting devices including a hook needle, a looper, a loop taker and a thread measuring pull-off, in combination with means including a pair of thread locks, one mounted along the path of the thread in the machine in front of the pull-off and one mounted along the path of the thread at the rear of the pull-off comprising fixed anvil blocks, clamp shoes acting on the thread engaged with the anvil blocks, independent spring pressed carrier arms for the clamp shoes, a common stud on which the carrier arms are rotatably mounted to enable separate movement of the clamp shoes toward and from the anvil blocks, and means including mechanism for actuating the pull-off away from the common stud to measure thread and toward the stud to give up thread.
12. A shoe sewing machine having stitch-forming and stitch-setting devices including a hook needle, a work support, a needle threading device, a presser foot for clamping the work against the work support, a loop taker acting to apply a stitch setting tension to the thread in a previously formed stitch and to give up thread during each sewing cycle as the threaded needle is being retracted from the work, a front thread lock, a rear thread lock and a pull-off acting on the thread between the locks, in combination with means including mechanism for actuating the pull-off comprising a bar rocked at one end while the rear lock is opened and the front lock closed, and rocked at the other end while the rear lock is closed and the front lock opened, means including a slider on the bar connected to operate the pull-off and controlled by the presser foot for shifting the slider along the bar toward that end of the bar which is rocked while the rear lock is opened to decrease the amount of thread measured as the thickness of the work decreases and to draw back thread from the loop taker in an increasing amount as the thread measured by the pull-off decreases.
13. A shoe sewing machine having stitch-forming and stitch-setting devices including a hook needle, a work support, a needle threading device, a presser foot for clamping the work against the work support, a loop taker acting to apply a stitch setting tension to the thread in a previously formed stitch and to give up thread during each sewing cycle as the threaded needle is being retracted from the work, a front thread lock, a rear thread lock and a pull-off acting on the thread between the locks, in combination with means including mechanism for actuating

ing the pull-off comprising a bar, two cam actuated mechanisms, one connected to one end of the bar to rock it while the rear lock is opened and the front lock closed and the other connected to the other end of the bar to rock it while the rear lock is closed and the front lock opened, and means including a slider on the bar connected to operate the pull-off and controlled by the presser foot for shifting the slider along the bar toward that end which is rocked while the rear lock is opened to decrease the amount of thread measured as the thickness of the work decreases and to draw back thread from the loop taker in an increasing amount as the amount of thread measured decreases.

14. A shoe sewing machine having stitch-forming and stitch-setting devices including a hook needle, a work support, a needle threading device, a presser foot for clamping the work against the work support, a loop taker acting to apply a stitch setting tension to the thread in a previously formed stitch and to give up thread during each sewing cycle as the threaded needle is being retracted from the work, a front thread lock, a rear thread lock and a pull-off acting on the thread between the locks, in combination with mechanism for actuating the pull-off comprising a bar, means including two cam actuated mechanisms, one connected to one end of the bar to rock it while the rear lock is opened and the front lock closed and the other connected to the other end of the bar to rock it while the rear lock is closed and the front lock opened, and means including a slider on the bar connected to operate the pull-off and controlled by the presser foot for shifting the slider along the bar toward that end which is rocked while the rear lock is opened to decrease the amount of thread measured as the thickness of the work decreases and to draw back thread from the loop taker in an increasing amount as the amount of thread measured decreases, said means including said cam actuated mechanisms acting together to impart a thread giving-up movement to the pull-off and at separate times in each sewing cycle to cause the pull-off to draw back thread.

15. A shoe sewing machine having stitch-forming and stitch-setting devices including a hook needle, a work support, a needle threading device, a presser foot for clamping the work against the work support, a loop taker acting to apply a stitch setting tension to the thread in a previously formed stitch and to give up thread during each sewing cycle as the threaded needle is being retracted from the work, a front thread lock, a rear thread lock and a pull-off acting on the thread between the locks, in combination with means including mechanism for actuating the pull-off comprising a curved bar, two cam actuated mechanisms, one of which is connected to one end of the bar to rock it while the rear lock is opened and the front lock closed, and the other of which is connected to the other end of the bar to rock it while the rear lock is closed and the front lock opened, a slider on the bar, a link pivotally connected between the slider and the pull-off with the center of pivotal connection for the link concentric with the curvature of the bar while the pull-off is in a position where no thread is measured, and means including connections between the presser foot and the slider for shifting the slider along the bar toward one end of the bar to increase the amount of thread measured as the thickness of the work increases and toward the other end of the bar to draw back thread from the loop taker in an increasing amount as the amount of thread measured decreases.

16. A shoe sewing machine having a main frame, a sewing shaft in the frame, stitch forming devices connected for actuation by the sewing shaft including a hook needle, a work support, a presser foot for clamping the work on the work support, mechanism for actuating the presser foot, and mechanism for measuring a length of thread for each stitch, in combination with means including a work caliper feeler mounted for

separate yielding movement relative to the presser foot actuating mechanism and connected to the thread measuring mechanism for adjusting the amount of thread measured as the work varies in thickness.

5 17. A shoe sewing machine having a main frame, a sewing shaft in the frame, stitch forming devices connected for actuation by the sewing shaft including a hook needle, a work support, a presser foot for clamping the work on the work support, mechanism for actuating the presser foot, and mechanism for measuring a length of thread for each stitch, in combination with

10 means including a work caliper feeler mounted for separate movement relative to the presser foot and connected to the thread measuring mechanism for adjusting the amount of thread measured as the work varies in thickness, said feeler projecting beyond the work-engaging surface of the presser foot in the direction of the work support to enable the feeler to register an increasing thickness of the work.

15 20 18. A shoe sewing machine having a main frame, a sewing shaft in the frame, stitch-forming devices connected for actuation by the sewing shaft including a hook needle, a work support, a presser foot for clamping the work on the work support, mechanism for actuating the presser foot, and mechanism for measuring a length of thread for each stitch, in combination with

25 means including a work caliper feeler mounted for separate movement relative to the presser foot actuating mechanism and connected to the thread measuring mechanism for adjusting the amount of thread measured as the work varies in thickness, said feeler being retractable during the work clamping action of the presser foot above the work-engaging surface thereof and away from the work support to enable the feeler to register a de-

30 35 30 crease in thickness of the work in the position at which the presser foot engages it.

19. A shoe sewing machine having a main frame, a sewing shaft in the frame, stitch-forming and work-feeding devices connected for actuation by the sewing shaft

40 40 including a hook needle acting at one position to penetrate the work and at a second position a stitch length from the first position to complete the stitch, a work support and a cooperating presser foot provided with a surface extending along the line of a seam approximately the same distance as that between the position in which

45 the stitch is formed and the position in which it is completed, mechanism for actuating the presser foot, and mechanism for measuring a length of thread for each stitch, in combination with means including a feeler

50 50 mounted for separate movement relative to the presser foot actuating mechanism to engage the work along the line of a seam in advance of the work-engaging surface of the presser foot and connected to the thread measuring mechanism for adjusting the amount of thread measured as the work varies in thickness, the feeler being movable beyond the work engaging surface of the presser foot in the direction of the work support to enable the feeler to register an increasing thickness of the work and being retractable above the level of the work-engaging surface of the presser foot to enable it to register a decreasing thickness of the work.

55 60 60 20. A shoe sewing machine having a main frame, a sewing shaft in the frame, stitch-forming devices connected for actuation by the sewing shaft including a hook needle, a work support, a presser foot for clamping the work on the work support, mechanism for actuating the presser foot, and mechanism for measuring a length of

65 thread for each stitch, in combination with means including a work caliper feeler mounted for separate movement relative to the presser foot actuating mechanism and connected to the thread measuring mechanism for adjusting the amount of thread measured as the work varies in thickness, and resilient means for pressing the feeler against the work to enable it to project in the

70 70 direction of the work support beyond or to lie flush with

the work-engaging surface of the presser foot as the thickness of the work changes.

21. A shoe sewing machine having a main frame, a sewing shaft in the frame, stitch forming devices connected for actuation by the sewing shaft including a hook needle, a work support, a presser foot for clamping the work on the work support, mechanism for actuating the presser foot, and mechanism for measuring a length of thread for each stitch, in combination with means including a work caliper feeler mounted for separate movement relative to the presser foot actuating mechanism and connected to the thread measuring mechanism for adjusting the amount of thread measured as the work varies in thickness, and means including a mechanical relay connected between the feeler and the thread measuring mechanism for adjusting the amount of thread measured as the work varies in thickness without impressing a surface-marring force on the feeler.

22. A shoe sewing machine having a main frame, a sewing shaft in the frame, stitch forming devices connected for actuation by the sewing shaft including a hook needle, a work support, a presser foot for clamping the work on the work support, mechanism for actuating the presser foot, and mechanism for measuring a length of thread for each stitch, in combination with means including a work caliper feeler mounted for separate movement relative to the presser foot actuating mechanism and connected to the thread measuring mechanism for adjusting the amount of thread measured as the work varies in thickness, a stop for limiting the relative move-

5

ment between the feeler and the presser foot and resilient means for pressing the feeler yieldingly against the work to enable it to register a decrease or an increase of work thickness within the range of its limited relative movement.

UNITED STATES PATENT OFFICE
CERTIFICATE OF CORRECTION

Patent No. 2,928,361

March 15, 1960

Fred Ashworth et al.

It is hereby certified that error appears in the printed specification of the above numbered patent requiring correction and that the said Letters Patent should read as corrected below.

Column 28, line 68, for "is indicated at 914 (Fig. 10) with a" read -- , such as that illustrated at 912 in Fig. --.

Signed and sealed this 25th day of October 1960.
